TELEPHONE SYSTEM

Edward S. Peterson, Elmwood Park, Ill., assignor
to Associated Electric Laboratories, Inc., Chi-
cago, Ill., a corporation of Delaware

Application May 29, 1937, Serial No. 145,543

39 Claims. (Cl. 178—26)

The present invention relates to telephone systems and more particularly to improvements in semi-automatic systems of the type adapted for use in communities, as, for example, in rural areas, wherein the telephone traffic is small.

In the type of system noted, separate exchanges or offices commonly known as satellite or suboffices are usually provided for supplying telephone service to small groups of subscribers' substations, when for economic reasons it is impractical to extend the subscribers' lines to the nearest main or central exchange. Such an office is illustrated and described, for example, in applicant's copending application Ser. No. 107,-15 581, filed Oct. 26, 1936, of which the present application is in part a division. Economy of system construction is further attained by routing all calls between the suboffice subscribers' lines and the central office subscribers' lines by way of a tandem office over trunk lines individually extending between each of the suboffices and the tandem office and between the tandem and central offices. The tandem office is usually conveniently located to serve a small group of subscribers' lines extending thereto from subscribers' substations located in the area immediately adjacent this office. This latter group of lines is usually quite small, consisting only of a few subscribers' lines of the party line variety having connected thereto magneto type substations of one form or another. The quality of service required by the few subscribers having substations on lines extending, respectively, to the tandem and satellite offices is inevitably quite low and insufficient economically to justify the form of equipment usually provided for serving the subscribers' needs.

It is an object of the present invention, therefore, to provide a telephone system of the general form noted which is extremely simple and economical in construction and arrangement, and which is entirely capable of providing adequate service to a limited number of rural subscribers.

More specifically, it is an object of the invention to provide in a system of the character specified small offices individually having automatic switching equipment arranged in an improved and simple manner, which equipment is capable of operating to set up the usual connections to and between any office line and the central exchange, and also, to set up any desired connection between any pair of subscribers' lines individually extending to individual ones of the small offices.

In general, the objects as set forth above are attained in accordance with the present invention

by providing a system of the form described wherein a trunk line extends between the central office and the tandem office, which trunk line is accessible to the subscribers' lines and suboffice trunk lines and to an operator's telephone at the central office, and, in which control means are provided in the tandem and suboffices responsive to impulsing means controllable by the central exchange operator for setting up connections between any pair of subscribers' substations included in the system. For the purpose of completing calls to and from the tandem office lines, i. e., the tandem office subscribers' lines and the suboffice trunk lines, line relays are included in the control means associated with the central exchange 15 trunk line, which line relays are individually associated with the lines terminating at the tandem exchange and with the automatic switching means of the central exchange trunk line. The line relays individually comprise windings included in the primary and secondary energizing circuits of the corresponding relays and are individually responsive to the initiation of a call on the associated line to connect the calling line to the central exchange trunk line. The control 20 means associated with the central exchange trunk line also include a stepping switch having a bank of contacts, one of which is included in each of the secondary energizing circuits of the line relays so that, when the wipers of the switch 25 are stepped to any one of a number of predetermined positions, the line relay corresponding to this position becomes energized to complete a connection between the calling and called lines. The stepping switch wipers are controlled by a 30 relay network wherein the relays thereof are so interrelated as to be responsive to impulses transmitted over the central exchange trunk line from the central exchange operator's impulsing device. Similar control means are included in each of the 35 suboffices, which means are individually associated with each of the suboffice trunk lines as pointed out in greater detail hereinafter. These control means are substantially similar to those disclosed in the above referred to copending application, but all of the novel features common thereto and to the present application are claimed herein.

The system arrangement is such that the central exchange trunk line is accessible to all of 50 the lines of the system for setting up connections therebetween. Since each connection is established by way of the central exchange trunk line and under the supervision of the central exchange operator, it is obvious that only a single 55

call can be handled by the tandem office equipment associated with the central exchange trunk line at any given time. To insure this result there are provided means responsive to the connection of the central exchange operator's telephone, any one suboffice trunk line, or any tandem office subscriber's line to the central office trunk line for preventing any of the remaining lines accessible to this line from being connected thereto in response to the initiation of a call thereon. This means, in the system to be described in detail hereinafter, comprises common cut-off relays responsive to the operation of any one of the line relays associated with the lines accessible to the central exchange trunk line, for interrupting the primary energizing circuits of all of these line relays, thereby to prevent these line relays from operating to connect their respective associated lines to the associated central office trunk line when calls are initiated on the associated lines. As pointed out in detail hereinafter, these common cut-off relays also comprise means for preventing the suboffice subscribers' lines from being connected to their respective associated suboffice trunk lines when the central exchange trunk line is seized by one of the tandem office subscribers' lines or at the central exchange operator's station. Also responsive to the operation of any one of the line relays associated with the central exchange trunk line is means for sending a signal back over a calling line to indicate to the calling party that the trunk line is idle, and timing means for releasing the connection between the calling line and the trunk line in case the operator's telephone is not connected to the trunk line within a given time interval after the operation of the line relay associated with the calling line. It is evident that the latter means is necessary in order to prevent any individual subscriber from permanently appropriating the single central exchange trunk line to the exclusion of all of the other lines having access thereto.

As noted above there are also provided control means in each of the various suboffices individually associated with the respective suboffice trunk lines, which means are responsive to operation of the central exchange operator's impulsive means to complete connections between the subscribers' lines common to the respective offices and between these lines and the subscribers' lines of the other offices. The nature of the equipment comprising these means is essentially the same as that included in the tandem office. This equipment differs slightly in that the subscribers' lines are arranged in two groups and the control means and stepping switch for selecting a particular called group is arranged to be responsive to two series of impulses or digits dialed at the central exchange operator's station, the first digit causing the selection of the group of lines including the called line and the second digit causing the selection of the particular called line in the selected group of lines. Aside from this difference in arrangement, the equipment in each of the suboffices is essentially the same as that embodied in the tandem office.

Various additional improvements in the circuit arrangement of the satellite and tandem office equipment are included in the system, which improvements are not specifically mentioned above and are for the purpose of simplifying the connections between the various relays of the control means and for reducing to a minimum the amount of apparatus employed.

The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figure 1 illustrates in partially schematic form a system of the type to which the present invention is applicable; Figs. 10 and 11, considered together, illustrate the apparatus and control circuits included in one of the satellite offices of Figure 1; and Figs. 4 and 5 illustrate the apparatus and control circuits embodied in the tandem office and the central exchange of Figure 1.

Referring now more particularly to Figure 1 of the drawings, the telephone system there illustrated comprises a central office 10, a plurality of satellite or suboffices, two of which are shown at 11 and 12, a tandem office indicated generally at 13, suboffice trunk lines 14 and 15 extending from the offices 11 and 12, respectively, to the tandem office 13 and a central office trunk line 16 connecting the tandem office 13 with the central exchange 10. The latter trunk line terminates at a repeater 20 associated therewith. The repeater 20 comprises secondary windings 22 and 23 coupled to primary windings 24 and 25, respectively, which primary coils are connected in series across conductors 26 and 27 comprising an intraoffice link line 28. This link line, which is considered as a part of the trunk line 16, is accessible through suitable switching means to each of the suboffice trunk lines 14 and 15 comprising, respectively, conductors 29, 30 and 31, 32, and also to a group of subscribers' lines extending to the tandem office, two of which are shown at 33 and 34 as including, respectively, conductors 35, 36 and 37, 38. With the arrangement shown a total of ten lines, irrespective of the distribution of tandem office subscribers' lines and suboffice trunk lines, may be accessible to the line 16.

In order to isolate the local batteries of the substations connected to the subscribers' lines, such, for example, as the lines 33 and 34, from the higher voltage common battery of the tandem office, these lines are not connected directly to the conductors of the line 28 but are connected to a link line 39 comprising conductors 40 and 41 which are respectively connected to the conductors 26 and 27 through direct current blocking condensers 42 and 43. The subscribers' lines, in the type of system described, are of the party line variety having connected thereto at least one and usually two or more subscribers' substations of the well-known local-battery type employing a magneto or hand generator for initiating calls therefrom. Thus, the line 33 has connected thereto a subscriber's substation A of this type and the line 34 has connected thereto two substations of the same type, indicated at B and C. Since this form of substation is well known in the art and the details thereof form no part of the present invention, the three substations noted have been shown schematically only.

Each of the suboffices 11 and 12 has extending thereto a plurality of subscribers' lines such, for example, as those indicated at 42', 43', 44 and 44' for the suboffice 11, and 45, 46 and 47 for the suboffice 12. These lines individually and respectively terminate at subscribers' substations shown schematically at D, E, K and F for the office 11 and G, H, and I for the office 12 and may individually be of the party line variety or the single

substation variety, depending upon the type of service required by the individual subscriber.

In addition to the portions of the system already described, there are provided control means associated with the various lines shown in Figure 1, which means are illustrated in detail in Figs. 2 to 5, inclusive, and operate in a manner such that a talking connection may be established between any pair of subscribers' lines, the individual ones of which individually terminate at any of the four offices shown. This means comprises automatic switching means included in the tandem office 13 and associated with the central exchange trunk line 18 thereof, as shown in Figs. 4 and 5, and switching means embodiment in each of the suboffices 11 and 12 and individually associated with the respective suboffice trunk lines 14 and 15 thereof, as shown in Figs. 2 and 3.

Neglecting for the present the details of the control means as shown in Figs. 2 to 5, inclusive, and considering the operation of the system generally, it is pointed out that the establishing and releasing of connections between any pair of the various subscribers' lines terminating at any of the four offices is entirely under the control of the operator located at the central exchange 10. Thus on a call from one of the tandem office subscribers' lines to another of the tandem office subscribers' lines such, for example, as a call from the substation A to the substation B, the party at the substation A removes his receiver from its hook and operates in a well-known manner his hand generator to apply ringing current to the line 33, which current causes a line relay to connect the calling line to the line 39, in case the central exchange trunk line 18 is idle, and is thereafter conducted over the lines 39, 28 and 18 to operate a signal device at the operator's station. When the operator's attention is attracted by operation of the signal device she connects her telephone to the line 18 to converse with the calling party and obtain the name or number of the called party, following which the calling party hangs up and the operator actuates the impulsing device at her station in accordance with the number of the called line. Such impulsing causes the automatic switching means associated with the trunk line 18 to respond and connect the line 34 to the link line 39, thereby establishing a loop between the calling and called parties over the lines 33, 39, and 34. The operator then applies ringing current by way of the lines 18 and 28 to both the lines 33 and 34, thereby to signal the calling party that a connection has been established and the called party that his telephone is being called. Since the line 34 is a two-party line, code ringing obviously must be used to inform the party B that he is being called and the party C that the call is meant for the party B.

Alternatively, if the call is to be extended to a subscriber's line in the central exchange or to a toll line, the operator may establish the required connection in the well-known manner through the operator's apparatus embodied in the central exchange. As a further alternative, if the call is intended for a subscriber in one of the suboffices 11 or 12, the operator, upon dialing a predetermined digit causes a suboffice trunk line such, for example, as the line 14, to be connected to the trunk line 18, following which additional digits are dialed to cause the automatic equipment in the called suboffice to extend the connection to the desired subscriber's line. Following this, ringing current is applied to the conductors of the trunk line 18 to signal the calling and called

parties that a connection has been established therebetween.

The operation of the system during calls initiated on one of the subscribers' lines terminating at the suboffices 11 and 12 is similar to that briefly described above, the primary difference being that the operation of the hand generators at any one of the substations associated with these lines causes successive operations of the automatic switching means in the associated suboffice and the tandem office, thereby to establish a connection between the calling party's substation and the operator's station and to signal the operator in the central exchange. Following this, the operator can, in a manner similar to that described above, extend the connection to the desired party regardless of the office in which the called line terminates. As will be pointed out hereinafter, the release of all connections except those involved in reverting calls is under the supervision of the central exchange operator.

Referring now to Figs. 2 to 5, inclusive, there are illustrated the control means or automatic switching means whereby the various operations as briefly described above may be carried out. As shown more particularly in Figs. 4 and 5, the control means in the tandem office 13 comprises means in the form of line relays such as the relays 310 and 320 individually associated with each of the subscribers' lines such as the lines 33 and 34 and line relays 330 and 340 individually associated with the trunk lines 15 and 14, respectively, for connecting the respective associated lines to the central office trunk line 18. Additional or secondary line relays 310 and 320 individually associated with the suboffice trunk lines 15 and 14, respectively, are provided, which are controlled by the relays 330 and 340, respectively, and serve a purpose to be described hereinafter. Each of the line relays 310, 320, 330, and 340 comprises a primary or first-operating circuit including one winding thereof bridged across the line conductors and energized during the initiation of a call on the associated line by the current from the hand generator at one of the substations on the line, a secondary or second-operating circuit including a second winding, and means comprising contacts responsive to the energization of the primary circuit for completing the secondary circuit. Thus, the line relay 310 has a primary circuit including the conductors 35 and 36 and the upper winding of the relay, a secondary circuit comprising the lower winding thereof and an armature 311 operated in response to the energization of the primary circuit for completing at the contact 312 the secondary circuit.

The individual secondary circuits of the several line relays comprise two branches, one branch being individual to the corresponding circuit and extending by way of a contact and associated wiper of an automatic or rotary stepping switch 401 and the other branch being common to all of the secondary circuits and extending over the conductors 318 and 319 through the winding of an additional relay 400 to battery. From the foregoing description it will be apparent that the primary and secondary circuits of each of the line relays are so connected and arranged that the operation of each relay is initiated by energization of its primary circuit, following which its secondary circuit is completed to complete the operation of the corresponding relay and to hold the operated relay in its operated position independently of its pri-

mary circuit. It will further be seen that the additional relay 400 is energized in response to the completion of the secondary circuit of any one of the line relays.

- 5 The last-mentioned relay, namely, the relay 400, comprises means for initiating the operation of; means for transmitting a waiting tone to a calling subscriber, timing means for disconnecting the trunk line from a calling subscriber's 10 line in case the central exchange operator fails to answer a call by connecting the operator's telephone to the trunk line 18 within a predetermined time interval after a calling line is connected to the trunk line, and means for interrupting the primary energizing circuits of all 15 the line relays in response to the operation of any one of these relays, thereby to prevent more than one calling line from seizing the trunk line 18 during any given time. Thus, the relay 400 20 includes an armature 401 for completing the energizing circuit of a tone relay 410, an armature 405 for completing a circuit for energizing the thermal relay 413 and an armature 403 for completing a circuit for energizing the common cut-off relay 350, which latter relay when operated completes at its armature 351 the circuit for energizing a second common cut-off relay 360. As will be noted, the second cut-off relay 360 25 includes armatures 361, 363, 365, 367, 369, etc., for interrupting the primary energizing circuits of the line relays associated with the subscribers' lines such, for example, as the lines 33 and 34 terminating at the tandem office, and the cut-off relay 350 includes armatures 353 and 356 for 30 interrupting the primary energizing circuits of the line relays 330 and 340, respectively, associated with the suboffice trunk lines 15 and 14, respectively.

In the central exchange, the trunk line 18 35 terminates at a repeater 466. This repeater comprises primary windings 447 and 448 connected in series across the conductors of the trunk line 18 and coupled to secondary windings 456 and 457 which are connected in series between the tip and sleeve contacts 458 and 459, respectively, of a jack 465. These windings are also connected across the windings of a signal device such, for example, as the drop 466. In addition, there is provided at the operator's station an impulsing device 467 for controlling, through the medium of a group of relays, the operation of the rotary switch 407. This device includes contact springs 468 and 469 for shunting, during a dialing operation, the windings of the drop 466 45 and interrupting or impulsing springs 478' and 479' extending, respectively, to a contact 464 included in the jack 465 and to the junction point between the primary windings 447 and 448 of the repeater 466.

60 As pointed out above, the equipment associated with the trunk line 18 comprises automatic switching means including the rotary stepping switch 407 and means for controlling this switch comprising the relays 420, 430, 450, 470, 480, 480', 485 and 485'. The enumerated relays are adapted to be responsive in a particular sequence or sequences to operations performed by the operator in the central exchange 10 and, more particularly, to operation of the operator-controlled impulsing device 467. The rotary switch 407 may be of any desired construction which comprises two sets of contacts, 478 and 479, wipers 428 and 429 for engaging the contacts of the contact sets 478 and 479, respectively, a rotary magnet 460 for 70 stepping the wipers 428 and 429 to predetermined

off-normal positions individually corresponding to the line such, for example, as the lines 14, 15, 33 and 34 extending to the tandem office, and a release magnet 462 under the control of off-normal springs 488, 489 for returning the wipers to their normal positions when an established connection is cleared out. As pointed out above, each of the contacts of the lower set 479 extends to one terminal of one of the windings included in the secondary energizing circuit of an associated relay, and each of the contacts of the upper set 478 extends to the winding terminal of one of the line relays associated with the trunk lines 14 and 15. Thus, the first, second, third, and tenth contacts of the lower contact set 479 are individually connected by conductors 414, 415, 416 and 417, respectively, to the terminals of the windings of the line relays 340, 330, 310 and 320, and the first and second contacts of the upper contact set 478 are individually connected by conductors 418 and 419 to the lower terminals of the windings of relays 480 and 485, respectively. As will be described in detail hereinafter, when the automatic switch 407 is stepped to any one of its predetermined positions, the secondary circuit of the line relay associated with the line corresponding to such position is energized, causing the relay to operate to connect the associated line to the trunk line 18. Thus, the line relays individually comprise means operated in response 30 to the operation of the automatic switch 407 to predetermined positions individually corresponding to the associated lines.

It is pointed out here that the line relays 420 35 is energized in response to the connection of the operator's telephone to the trunk line 18, over a circuit extending from battery at the contact spring 464, through the interrupting contact springs 478', 479' and the repeater winding 448, over the lower conductor of the trunk line 18, 40 and through the lower repeater winding 23 and the winding of the relay 420 to ground. This relay, in combination with the relays 430 and 440, comprises means for interrupting the operation of the tone relay 410 and for arresting the operation of the timing means comprising the thermal relay 413. Thus, when the relay 420 operates, it causes the sequential operation of the relays 430 and 440, the first of which interrupts at its armature 431 and associated contact 432 the circuit 50 for energizing the thermal relay 413 and the last of which interrupts at its armature 441 the circuit for energizing the tone relay 410.

As indicated in Figure 1, the suboffice trunk line 14 terminates at the suboffice 11 to which 55 extend subscribers' lines such, for example, as the lines 42' and 43' and the trunk line 15 terminates at the suboffice 12 to which extend subscribers' lines including the lines 45, 46 and 47. The switching and control equipment included in 60 these two offices is identical and for that reason only the equipment included in the office 11 has been shown in detail. Each suboffice is capable of serving two groups of subscribers' lines, each including ten lines, and the control equipment is arranged to be responsive to two digits dialed at the central exchange operator's station to select the desired group of lines and the desired called line in the selected group of lines. As shown in Fig. 3, the line 14 terminates in the 70 suboffice 11 at a repeater 209 having secondary windings 217 and 218 connected in series between the conductors 29 and 30 of the line 14 by means of a condenser C8, and primary windings 207 and 208 connected in series between the line conduc- 75

tors 102 and 103 of a link line 115. Each of the subscribers' lines terminating at the suboffice 11 is adapted to be connected to the link line 115 through the medium of a line relay associated with the corresponding subscriber's line. Thus, the subscriber's line 42' may be connected to the line 115 by means comprising a line relay 120. Similarly, the subscribers' lines 43', 44 and 44' may be connected to the line 115 by means comprising the relays 110, 140 and 150, respectively.

Each of the enumerated line relays comprises a primary or first-operating circuit including the talking conductors of the associated line, and a secondary or second-operating circuit which is completed in response to completion of the primary energizing circuit of the same relay and also in response to the operation of a minor or rotary stepping switch 225 to a predetermined position. It will be seen that the line relays for individually connecting the subscribers' lines such, for example, as the lines 42', 43' and 44 to the link line 115 constitute a group of relays, only one of which should, at any given time, be responsive to the initiation of a call on its associated line. For this reason, the primary energizing circuits for the group of line relays associated with the lines 42', 43', etc., included in the first group of ten subscribers' lines, individually include means responsive to the operation of common cut-off relays for permanently interrupting the primary energizing circuits so long as the associated cut-off relay is operated. Thus, each of the line relays 110, 120, etc., has a primary energizing circuit which includes an armature such, for example, as the armatures 131, 132, 133, etc., under the control of a common cut-off relay 130. Similarly, the line relays, such as relay 140, associated with the lines of the second group of ten subscribers' lines, include, in their respective primary energizing circuits, armatures such, for example, as the armatures 161, 162, 163, etc., under the control of a common cut-off relay 160.

The secondary circuits for the line relays 110, 120, 140, 150, etc., have a common portion which includes the winding of an additional relay 200. This latter relay comprises contacts for completing, when the relay 200 is operated, the energizing circuit of the common cut-off relay 130. Also responsive to the operation of the relay 200 is timing means comprising a thermal relay 294 for effecting the release of the trunk line 14 from a calling subscriber's line in case the operator at the central exchange fails to answer the call within a predetermined time interval after the calling line is connected to the trunk line 14.

Thus, when the relay 200 operates, it completes, at its armature 202, an obvious circuit for energizing the thermal relay 294. In addition, the relay 200 includes contacts for controlling the operation of a tone relay 205 having self-interrupting contacts for periodically short-circuiting one winding thereof such that, when energized, this relay operates in the manner of a buzzer to cause, by induction, an alternating voltage to be developed across its upper winding and impressed across the conductors 102 and 103. The operation of the tone relay 205 and the timing means comprising the thermal relay 294 is interrupted by means including the relays 290, 280, and 270, which operate, in the order named, in response to the operation of the switch 407 in the tandem office to a position corresponding to the suboffice trunk line 14. Thus, when the relay 290 operates it completes, at its armature 291 and associated upper contact, a circuit for energizing the relay 280, which relay in turn operates to complete a circuit for energizing the relay 270. When the last-mentioned relay operates it interrupts at its armature 274 the circuit for energizing the tone relay 205 and, at its armature 273, interrupts the operating circuit for the thermal relay 294, thereby arresting the operation of this relay.

In order to effect the connection of a called line to the trunk line 14 there is provided automatic switching means in the suboffice 11 associated with this trunk line and responsive to impulses transmitted over this line from the impulsive device 467 at the operator's station. This means comprises the minor switch 225 for controlling the operation of the two groups of line relays and is of the rotary stepping type including wipers 213 and 214 adapted to be stepped, by an operating magnet 212, to predetermined positions individually corresponding to the individual subscribers' lines such, for example, as the lines 42', 43' and 44, and to be restored to normal by means including a release magnet 215 and off-normal springs 216. The wipers 213 and 214 are adapted to engage, respectively, contacts included in contact sets 226 and 221. Each contact of each of the two contact sets corresponds to one of the predetermined positions of the switch wipers 213 and 214 and is connected to one terminal of a winding included in the secondary circuit of one of the line relays. Thus, the first and second contacts of the contact set 226 are connected by conductors 106 and 107, respectively, to the lower terminals of the upper windings of line relays 110 and 120, respectively. It will be observed that each of the two contact sets includes ten contacts, which means, of course, that the minor switch 225 is capable of connecting any one of twenty subscribers' lines to the trunk line 14.

The contact wipers 213 and 214 of the minor switch 225 are adapted to be connected to ground selectively to complete the secondary energizing circuits of the various line relays through the armatures 222 and 211 of relays 220 and 210, respectively, and the armature 275 of the hold relay 270. With this arrangement, the armature 222 is adapted selectively to connect ground to one of the two wipers 213 and 214, depending upon the condition of the relay 220, which latter relay is energized in response to the dialing of one predetermined digit at the central exchange operator's station, and is in a de-energized condition when another predetermined digit is dialed at the operator's station. From the foregoing description it will be apparent that the line relays such, for example, as the relays 110 and 120, individually comprise means responsive to the operation of the automatic switch 225 to a predetermined position for connecting the subscribers' lines corresponding to these line relays to the trunk line 14 of which the link line 115 is considered a part.

The automatic switching equipment associated with the trunk line 14 includes, in addition to the minor switch 225 and the enumerated relays 210, 220, 270, 280, and 290, relays 230, 240, 250, and 260, all of which comprise means for controlling the operation of the minor switch 225 and operate in a predetermined sequence or predetermined sequences in response to operations performed by the central exchange operator, and, more particularly, in response to the operation of the impulsive device 467.

From the foregoing description it will be ap-

parent that the lines such, for example, as the lines 14, 15, 33, and 34, constitute a group of lines accessible only to the central office trunk line 18. Also accessible to this line are the central exchange operator's telephone and a group of lines in the suboffice 11 comprising the lines 42' and 43'. In order to prevent any one of the last-mentioned group of lines from being connected to the central office trunk line 18 when the latter line is busy in connection with a call in which the suboffice trunk line 14 is not involved, there is provided means for interrupting, under the conditions stated, the primary circuits of the line relays 110, 120, etc., associated, respectively, with the twenty suboffice subscribers' lines. This means comprises the common cut-off relay 350, which, upon operating, opens at its armature 358 the primary circuit of the relay 340 and closes an operating circuit for the line relay 290. The relay 290, upon operating initiates the sequential operation of the relays 280, 270, 130, and 160, whereby the primary circuits of all the line relays 110, 120, 140, etc., are interrupted.

Each of the common batteries included in the individual suboffices is of a lower voltage than the common battery included in the tandem office 13, and provisions are made whereby the suboffice batteries may be charged from the tandem office battery over the suboffice trunk lines. Thus, when the line 14 is idle, the line relay 380 and the common cut-off relay 160 associated therewith are in their respective restored positions so that the conductor 29 of this line is connected by way of the armature 381 and the lower contact 382 of relay 380 to the tandem office battery, and is also connected by way of a conductor 101 and the armature 164 of the common cut-off relay 160 to the battery of the suboffice 11. This circuit constitutes a circuit for charging the battery located in the suboffice 11 from the tandem office battery during those periods when the trunk line 18 is inactive.

As pointed out previously, the control equipment of the system as described in detail above is capable of operating under the central exchange operator's supervision to connect any one of the lines terminating at any one of the four exchanges to any other line terminating thereat, thereby to establish a talking loop between the telephones associated with the connected lines.

Initiation of a call on a tandem office subscriber's line

Thus, if a call is initiated on the line 34 from the substation B to one of the other subscribers' lines of the system, the relay 320 is energized to connect this line to the link line 39, which link line is considered to be a part of the central office trunk line 18. This relay is operated in two steps. Thus, with the substation B idle, the primary circuit of the relay 320 including the conductors 37 and 38, is prepared. This circuit extends from the conductor 37 through the upper winding of the relay 320 and the armature 369 of the common cut-off relay 360 to the armature 325 connected to the conductor 38. When the subscriber at the calling substation B operates his hand generator in the conventional manner, ringing current flows over the above circuit causing the relay 320 partially to operate to close its "X" contacts comprising the contact 322 and the associated contact on the armature 321. These contacts comprise means for completing the secondary energizing circuit of the relay 320,

this circuit extending from ground at the contact 322 by way of the armature 321, the lower winding of the relay 320, the conductor 318, the conductor 319, the armature 343 and through the winding of the relay 400 to battery. When the secondary circuit of the relay 320 is completed in the above-described manner, the relay 320 completes its operation and, at its armatures 323 and 325, connects the conductors 37 and 38, comprising the line 34 to the conductors 40 and 41, respectively, comprising the link line 39 included in the trunk line 18. At its armature 325 and back contact 326 the relay 320 interrupts its primary circuit, the relay now being held operated by virtue of the energized condition of its secondary circuit.

As noted previously, the relay 400 comprises means responsive to the operation of the relay 320 for interrupting the primary circuits of all the line relays such as the relays 310, 320, 330, 20 and 340, for initiating the operation of the tone relay 410, and for initiating the operation of the timing means comprising the thermal relay 413. Thus, the relay 400 energizes in series with the lower winding of the relay 320 when the secondary energizing circuit of the latter relay is completed and in turn completes, at its armature 401, an obvious circuit for energizing the upper winding of the tone relay 410. At its armature 405 and associated contact 406, the relay 400 also completes an energizing circuit for the thermal relay 413, which circuit extends from ground at the armature 431 of the relay 430, by way of the contact 432, the armature 405 and associated contact 406, and through the resistor 439 of the thermal relay 413 to battery. The signal means comprising the tone relay 410, when energized in the above-described manner, operates in the manner of a buzzer by virtue of its self-interrupting contacts 411 and 412 and induces in its lower winding an alternating voltage which is applied across the conductors 26 and 27 through the condenser 449. This voltage causes current to flow back over the loop extending to the subscriber's substation B and generates a tone in the receiver at this substation to indicate to the calling party that the trunk line 18 is idle and has been seized. The calling party upon receiving this indication again actuates the hand generator at the substation B to project ringing current over the lines 34, 39, 28 and 18, and thus energize the drop 466. The operator is thus informed that an incoming call awaits attention.

The primary circuits of the various subscribers' line relays are interrupted through the operation of the common cut-off relays 350 and 360 which respond, in the order named, to operation of the relay 400. Thus, when the relay 400 operates, it completes, at its armature 403 and associated contact 404, a circuit extending by way of the conductor 499 for energizing the relay 350, and the latter relay completes, at its armature 351 an operating circuit for the relay 360. Both cut-off relays are now operated so that the primary circuits of the subscribers' line relays 310, 320, 65 etc., are interrupted at the armatures 361, 363-369 and associated contacts of the relay 360, and the primary circuits of the line relays 330 and 340 are interrupted at the armatures 353 and 356 and associated contacts 354 70 and 357, respectively, of the relay 360. With the respective primary circuits of the various line relays interrupted in the manner described, these relays are not responsive to calls initiated on their respective associated lines. Also, and 75

as was pointed out above, the operation of the cut-off relay 350 causes the sequential operation of the relays 290, 280, 270, 130 and 160 in the suboffice 11, so that the subscribers' substations on lines terminating at the suboffice 11 are prevented from seizing the trunk line 14 leading to the tandem office. Similarly, the apparatus in the suboffice 12 operates to prevent the seizure of the trunk line 15 by a suboffice subscriber when the central exchange trunk line 18 is busied in the manner described above.

When the thermal relay 413 is energized over the above-traced circuit, it starts to operate and, unless its operation is interrupted within a pre-determined time interval, closes its bimetallic element 487 to the associated contact to complete an obvious circuit for energizing the relay 420. This latter relay, at its armature 423 and associated contact 424, in turn completes an obvious energizing circuit for the slow-to-release relay 430. When the relay 430 operates, it completes, at its armature 431 and associated contact 433, an obvious energizing circuit for the relay 440. The relay 440, upon operating, opens at its armature 443, the original secondary energizing circuit for the relay 320. Before this occurs, however, a shunt is connected around the armature 443 at the armature 436 of the relay 430 so that the secondary circuit of the line relay 320 remains closed. The relay 430, upon operating, also interrupts at its armature 431, the energizing circuit for the thermal relay 413. After a short interval required for cooling the element 487, this element moves away from its associated contact to interrupt the energizing circuit for the relay 420, permitting this relay to restore and break at its armature 423 the operating circuit for the relay 430. This latter relay in turn restores, opening the energizing circuit for the relay 440 and the shunt comprising the armature 436 around the armature 443. Due to the slow release characteristic of the relay 440, the shunt around the armature 443 is opened before this relay restores, thereby interrupting the previously-traced circuit for energizing the line relay 320 and the relay 400 in series. The relay 320 thereupon restores, opening its contacts 321 and 322 to further interrupt its secondary circuit and to disconnect the line conductors 37 and 38 from the link line conductors 40 and 41. When the relays 400 and 440 restore, the operating circuit for the cut-off relay 350 is interrupted, thereby to cause the sequential restoration of this relay and the cut-off relay 360.

55 The above-described operation for the timing means comprising the relay 413 is based on the assumption that the connection as established by way of the trunk line 18 to the operator's station is not answered within a predetermined time interval. If the operator answers the call within the time interval required for operation of the thermal relay 413 by inserting the plug terminating the operator's telephone in the jack 465, the drop 466 is restored to its normal position and a circuit is completed for energizing the relay 420, which relay operates to cause the energization of the relay 430, resulting in the interruption of the energizing circuit for the thermal relay 413 at the armature 431 to arrest the operation of the timing means. The above-mentioned energizing circuit for the relay 420 extends from battery at the jack spring 464 through the interrupting springs 418' and 418" of the impulsive device 467, the lower winding 448 of the repeater 446, the lower conductor of

the trunk line 18, the lower winding 23 of the repeater 20 and through the winding of the relay 428 to ground. The relay 420 not only operates to complete an energizing circuit for the relay 430 at its armature 423 but, in addition, closes its armature 421 to the contact 422 and thereby prepares a circuit for applying battery to the respective lower conductors of the suboffice trunk lines 14 and 15. As will be pointed out herein-after, the application of battery to the line conductor 50, associated with the trunk line 14, by way of the resistor 500, constitutes the final step in the operations leading to the energization of the line relay 280 associated with the trunk line 14 on a call to a subscriber's line terminating at the suboffice 11.

When the relay 430 operates following the operation of the relay 420, it completes, at its armature 431, an energizing circuit for the relay 440 and closes its armature 434 to the associated contact 435 to prepare a circuit for energizing the slow-to-release relay 450 and the rotary magnet 460 of the rotary stepping or automatic switch 407. In addition, the relay 430 closes, at its armature 436, the previously-mentioned shunt around the armature 443 and further prepares, at its armature 438, the above-noted circuit for applying battery to the conductors of the sub-office trunk lines 14 and 15.

When the relay 440 operates, in response to the completion of its energizing circuit as described above, it interrupts, at its armature 441, the energizing circuit for the tone relay 410 and, at this same armature, connects multiple ground to the conductor 499 included in the operating circuit of the common cut-off relay 350. At its armature 442, the relay 440 prepares a holding circuit for the line relays such, for example, as the relay 290 associated with the suboffice trunk line 14 and, at its armature 443, it interrupts the original secondary circuit for the line relay 320. The relay 440, upon operation, also prepares, at its armature 444, a holding circuit for the relay 470 and, at its armature 445, an energizing circuit for the line relay associated with the called line terminating at the tandem office.

When the tone relay 410 is de-energized in the above-described manner, the resulting interruption of the signal indicates to the calling party that the operator has answered and this party may, accordingly, transmit to the operator the information concerning the name or telephone number of the called party. It is pointed out that the control equipment associated with the trunk line 18, and more particularly the control apparatus for the rotary switch 407, is now conditioned to be responsive to impulses transmitted from the impulsing device 461. 50 55

*Completion of the call to another tandem office
subscriber's line* 60

Following the despatch of the information as noted above, the calling party hangs up and the operator actuates the impulsing device 467 to cause the rotary switch 401 to step its wipers to the position corresponding to the called tandem office subscriber's line. Thus, if the substation A is being called, the digit 3 is dialed at the impulsing device 467, causing the previously-traced energizing circuit for the relay 420 to be interrupted three times. During each interruption, this relay restores, opening, at its armature 423 and associated contact 424, the energizing circuit for the relay 480 and completing the previously prepared and obvious energizing circuit for the 75

slow-to-release relay 450 and the rotary magnet 460. Due to the slow release characteristic of the relays 430 and 450, these relays remain operated during the impulsing. The first of these relays is held operated at conclusion of the impulsing by virtue of the closure of the interrupting springs 478' and 479' included in the impulsing device 467. Each time the energizing circuit of the magnet 460 is energized, the wipers 428 and 429 of the rotary switch 407 are stepped one step so that, at the end of the third impulse, they rest, respectively, on the third contact of each of the contact sets 478 and 479.

At the beginning of the first impulse the slow-to-release relay 450 operates to prepare, at its armature 453 and associated contact 454, a circuit for energizing the relay 485 and to interrupt, at its armature 451, a point in the circuit extending from ground at the off-normal springs 488, 489 for energizing the relay 470. Since the relay 450 remains operated during the impulses following the first impulse, the last-mentioned circuit is maintained open during the remaining impulses of the first digit. At the end of the first impulse, the off-normal springs 488, 489 of the rotary switch 407 are closed to prepare the above-noted circuit for energizing the relay 470, this circuit being completed when the relay 450 restores at the end of the first digit and extending from ground at the spring 488 by way of the elements 489, 451, 452, and the winding of the relay 470 to battery. Restoration of the relay 450 also opens, as at armature 453, the prepared point in the circuit for energizing the relay 485. When the relay 470 operates, it completes, at its armature 472, the previously prepared locking circuit for itself and, at its armature 471, prepares a circuit for energizing the relay 485. At its armature 471, the relay 470 interrupts the energizing circuit for the rotary magnet 460 and, at its armature 476, prepares an obvious energizing circuit for the release magnet 462. The relay 470 also completes the secondary circuit for the line relay 310 associated with the subscriber's line 33, this circuit extending from ground at the armature 445 by way of the armature 474, the wiper 429, the third contact of the contact set 479, the conductor 416, through the lower winding of the relay 310, over the conductors 318 and 319 and through the winding of the relay 400 to battery.

The relay 310 operates in response to the completion of its secondary circuit in the above-described manner and, at its armatures 313 and 315, connects the conductors 35 and 36 comprising the line 33 to the conductors 40 and 41 comprising the link line 39. This relay also completes, at its armature 311 and associated contact 312, a holding circuit for itself and opens, at its armature 315, a further point in its primary circuit. With the system in this condition, talking loops are completed between the calling and called subscribers' lines and the central exchange operator's telephone, the latter loop including the trunk line 18. The operator may now indicate that such a connection has been established by applying ringing current in a well-known manner between the secondary terminals of the repeater 446, which current is transmitted through the repeater 446 over the trunk line 18, through the repeater 20, and over the two link lines 28 and 39 and the two subscribers' lines 34 and 33 to the signal devices at the substations of the calling and called lines.

Since only one substation is associated with the line 33, code ringing is not required. If, however, this line were a party line, selective code ringing could be employed to inform the proper party on the line that his substation was being called. Following the operation of the signal devices at the calling and called substations, the calling and called parties may answer the call and converse.

The operator may maintain the operator's telephone connected to the established talking loop to monitor the connection if desired. In any case, it is necessary that the plug associated with the operator's telephone be retained in the jack 465 in order to hold the previously-traced energizing circuit for the relay 420 completed and thus prevent the sequential restoration of the relays 430 and 440, in the manner noted above, to interrupt the holding circuit for the operated line relays 310 and 320. It is pointed out that transmission battery is supplied to the telephones of the calling and called parties by local batteries located at each of these substations.

Release of the established connection

When the conversation between the calling and called parties over the connection as established above is terminated, either of these two parties may inform the operator by operating his hand generator to transmit current over the central exchange talking loop comprising the trunk line 18, thereby to cause the reoperation of the signal device comprising the drop 466. The operator then removes the plug associated with the operator's telephone from the jack 465 to interrupt the previously-traced energizing circuit for the relay 420. This relay restores, causing the sequential restoration of the relays 430 and 440 in the order named, thereby momentarily interrupting, in the previously-described manner, the secondary energizing circuits for the line relays 310 and 320. The latter relays in turn restore, further to open, at their respective armatures 311 and 321, the respective secondary circuits therefor. These relays also disconnect, in an obvious manner, their associated subscribers' lines from the link line 39.

When the secondary circuits for the relays 310 and 320 are interrupted, the relay 400 restores, to open, at its armature 405, a point in the circuit for energizing the thermal relay 418. The relay 400 also opens, at its armature 403, the previously-traced holding circuit for the common cut-off relay 350. The latter relay in turn restores, opening the circuit holding the common cut-off relay 360 operated. The two cut-off relays restore to recomplete the primary circuits for all of the line relays individually associated with individual ones of the subscribers' lines and suboffice trunk lines terminating at the tandem office. When the relay 350 falls back, it interrupts at its armature 356 and associated contact 358, the circuit, traced hereinafter, holding the line relay 290 in the suboffice 11 energized, thereby to initiate the sequential restoration of this relay and the relays 280, 270, 130 and 160. When the two last-named relays restore, the primary circuits for the line relays associated with the subscribers' lines terminating at the suboffice 11 are completed, thereby to condition these relays to be responsive to calls initiated on the respective associated lines. In a similar manner the primary circuits of the line relays associated with the subscribers' lines extending to the suboffice 12 are recompleted.

When the relay 420 restores, it recomplete the circuit for energizing the slow-to-release relay 450, causing this relay to operate and interrupt at its armature 451 the original circuit for energizing the relay 470. The relay 450 also completes, at its armature 453, a circuit for energizing the relay 485, causing this relay to operate, but without effect at this time. The relays 430 and 440 both restore before the relay 450 falls back and the relay 440 completes, at its armature 445 and associated lower contact, a circuit for energizing the release magnet 462, causing this magnet to operate its armature and permit the switch 407 to restore its wipers to their normal or home positions and to open its off-normal springs 488, 489. At its armature 444, the relay 440 interrupts the holding circuit for the relay 470 so that shortly after the release magnet 462 is energized, the relay 470 falls back to interrupt at its armature 476 the energizing circuit for this magnet. The arrangement is such that the relay 450 restores shortly after the relay 430 falls back, thereby to reprepare, at its armature 451, the original circuit for energizing the relay 470, this circuit being maintained open, when the switch 407 restores, at the off-normal springs 488, 489. When the relay 470 falls back, the circuit for energizing the relay 485 is broken, permitting this latter relay to restore. Thus, all of the relays illustrated in Figs. 4 and 5 are restored to normal, and the system is in its normal idle condition.

Reverting calls to tandem subscribers' substations

In the event the call initiated on the line 34 from the subscriber's substation B is to be extended to a substation on the same line such, for example, as the substation C, the call is initiated to cause the sequential operation of the line relay 320 and the relays 400, 410 and 413 in the manner described above. When the line relay 320 operates, it connects the associated subscriber's line 34 by way of the link lines 39 and 28 to the trunk line extending to the operator's station in the central exchange, so that further operation of the calling subscriber's hand generator causes operation of the drop 466. After the operator has answered the call and received the information that the substation C is desired, the party at the substation B hangs up and the operator at the central exchange transmits coded ringing current back over the established loop including the line 34 to signal the party at the substation C that this substation is being called, following which the calling and called parties may converse over the connection consisting solely of the line 34.

It is pointed out that the trunk line 18 and its associated equipment need not be tied up on reverting calls. Indeed, if all of the parties on a particular line and the operator are familiar with the coded calls corresponding to the substations associated with such lines, there is no necessity for the operator's taking any part in establishing the connection since operation of the hand generator at the substation B, for example, causes operation of the signal device or bell at the substation C. Although such operation of the hand generator at the substation B causes the energization, in the previously described manner, of the line relay 320, which relay initiates the operation of the relays 400, 410 and 413, the latter relay operates in the previously described manner to cause, after a predetermined time interval, the restoration of all of these relays and the disconnection of the calling subscriber's line from the trunk line 18. It is thus apparent that reverting

calls or calls between substations common to a party line need not tie up the equipment associated with the central exchange trunk line 18. If desired, busy signal means of any desired form may be associated with such lines to signal the central exchange operator that a particular line is busy in connection with a reverting call of the type noted, thereby to prevent the operator from connecting another subscriber's line to the busy party line.

10

A call from a tandem office subscriber's line to a line terminating at the central exchange

In the event a connection is to be established between a substation associated with one of the tandem subscribers' lines and a line terminating at the central exchange 10, the operations necessary to signal the central exchange operator and to establish a talking connection from the calling subscriber's substation to the operator's telephone are exactly the same as those described above. When the operator answers and learns from the calling party the name or number of the party desired, the latter party may be called and the connection between the calling and called parties completed in the same manner as that conventionally employed in manual exchanges, the operation of which is well understood in the art. The release of such a connection is effected by exactly the same operational steps as those described above in connection with calls from one tandem subscriber's line to another tandem subscriber's line.

15

20

25

30

35

Call from one suboffice subscriber's line to another line terminating at the same suboffice

As pointed out previously, not only are connections between the tandem office subscribers' lines completed and released under the central exchange operator's supervision, but also, connections between lines terminating at any of the suboffices are completed in the same manner. Thus in the event a party at the substation D desires to converse with the subscriber E, the call is initiated by the first-mentioned subscriber operating his hand generator to energize the primary circuit for the line relay 120. Assuming that the trunk lines 14 and 18 are idle, the primary circuit of the relay 120 is energized, this circuit extending from the hand generator at the calling substation by way of the subscriber's line conductor 192, the armature 122, the armature 131 of the common cut-off relay 130, the lower winding of the line relay 120, and over the subscriber's line conductor 193 to the hand generator. The line relay 120 operates, in response to its energization over the above-traced circuit, and, at the X contacts associated with its armature 123, completes its secondary circuit, this latter circuit including the winding 60 of the relay 200 and extending from ground by way of the armature 123, the upper winding of the relay 120, the conductor 104, the armature 271 and the winding of the relay 200 to battery. At its armature 122, the line relay 120 opens its primary circuit only after the above-traced locking circuit is completed and, at its armatures 121 and 122, connects the subscriber's line conductors 192 and 193 to the link line conductors 103 and 102, respectively.

40

45

50

55

60

65

70

75

When the relay 200 operates, in response to its energization in series with the upper winding of the relay 120, it completes at its armature 201 an obvious circuit for energizing the cut-off relay 130. At its armature 203, the relay 200

completes a circuit for energizing the tone relay 205. The last-mentioned relay, by virtue of the self-interrupting contacts associated with its armature 206, operates buzzer fashion to induce in its upper winding waiting tone current which is transmitted over the lines 115 and 42' to the receiver at the calling subscriber's substation. At its armature 202, the relay 200 completes an obvious circuit extending from ground at the armature 273 for energizing the heating resistor embodied in the thermal timing relay 204. The last-mentioned relay, in cooperation with the relays 290, 280 and 270, operates in a manner identical with that described above, for the corresponding elements 413, 420, 430 and 440, respectively, of the tandem office, to release the trunk line 14 and the control apparatus associated therewith in the event the central exchange operator does not answer the call within the time interval required for the operation of the relay 204. At its armature 204, the relay 200 interrupts a point in the charging circuit for the suboffice battery.

When the cut-off relay 130 operates in response to its energization, as described above, it completes, at its armature 134 an obvious circuit for energizing the cut-off relay 160. With the two relays 130 and 160 operated the primary circuits for the line relays 110, 120, 140, etc., are interrupted at the armatures 131, 132, 133, etc., and the armatures 161, 162, 163, etc., thereby to guard the line 14 from seizure by another party during the time it is occupied with the call being described.

From the foregoing description, it will be seen that in response to the operation of the hand generator at the station D, the line relay 120 is energized and locked to connect the subscriber's line 42' to the trunk line 14. In order more fully to describe the circuit operations, it will now be assumed that the central exchange trunk line 18 is busy and the suboffice trunk line 14 is idle at the time the calling party at the station D operates his hand generator. If this condition prevails, the common cut-off relay 350 is in its operated position by virtue of the energized condition of the relay 440. As a consequence, the line relay 290 is energized over a circuit extending from battery at the contact 358 by way of the armature 356, the contact 385, the armature 386, the trunk line conductor 30, the repeater winding 218 and the winding of the relay 290 to ground. With the relay 290 operated the relays 280, 270, 130 and 160 are also necessarily energized over more or less obvious circuits traced in detail hereinafter. With the common cut-off relays 130 and 160 operated the primary circuits for the line relays individually associated with the respective subscribers' lines are open and, consequently, the ringing operation of the party at the substation D, or any other substation, is without effect. The calling party failing to get waiting tone under these conditions must necessarily repeat the ringing operation until waiting tone is returned to him when he is informed that the central exchange operator has been signalled.

Returning now to the point in the operation when the line relay 120 is operated to connect the subscriber's line to the trunk line 14, the continued operation of the hand generator at the calling substation transmits ringing current through the repeater 208 and over the trunk line conductors 29 and 30 to cause the energization of the primary circuit for the line relay 340. More specifically, this circuit extends over the calling subscriber's line 42', the link line 115,

and the trunk line 14 to the bridge comprising the condenser 346, the lower winding of the relay 340, the armature 345 and associated contact 347 of the relay 340, and the armature 358 and associated contact 357 of the relay 350. In response to such energization, the relay 340 partially operates to complete, at its armature 341 and contact 342, its secondary energizing circuit including the winding of the relay 400, this circuit extending from ground at the contact 342, through the upper winding of the relay 340, over the conductors 318 and 319 and through the winding of the relay 400 to battery. The relay 340 now completes its operation to open, at its armature 345 and associated contact 341, its previously-traced primary circuit and to close, at its armature 343, an obvious circuit for energizing the line relay 380. The latter relay in turn operates to connect, at its armatures 381 and 384, the trunk line conductors 29 and 30 to the link line conductors 26 and 27, thereby to complete a connection between the calling subscriber's substation and the central exchange operator's station. Operation of the armature 381 also disconnects charging battery from the negative trunk line conductor 29 at the contact 382 and operation of the armature 384 disconnects the armature 386 from its associated contact 385 to open a further point in the primary circuit for the relay 340 and to prevent battery from the resistor 336 from being applied to the conductor 30, thereby to energize the relay 290, when the cut-off relay 350 operates.

Continuing now with the operation of the apparatus in the tandem office 13, the relay 400 operates simultaneously with the complete operation of the relay 340 to initiate the operation of the timing means comprising the relay 413, to complete the energizing circuit for the tone relay 410 and to complete the circuit for energizing the common cut-off relay 350, all in the manner described in connection with calls from one tandem subscriber's line to another tandem subscriber's line. The relay 350, in addition to completing a circuit for energizing the relay 360, operates its armatures 353 and 356 into engagement with the contacts 355 and 358, respectively. Since the apparatus included in the suboffice 12 is identical with that embodied in the suboffice 11, it will be understood, from the preceding description, that the operation of the relay 350 to apply, at the armature 353, battery to the trunk conductor 32, causes the apparatus in the suboffice 12 to operate to interrupt the primary circuits of all of the line relays individually associated with the subscribers' lines 45, 46, 47, etc., extending to this suboffice. Thus, the apparatus included in the suboffice 12 is conditioned so that the trunk line 15 cannot be seized by any of the subscribers' lines terminating at this office. The relay 360, upon operating, interrupts the primary energizing circuits of the line relays associated with the tandem subscribers' lines, such, for example, as the lines 33 and 34.

Continued operation of the hand generator at the calling subscriber's substation causes ringing current to be transmitted over the loop as established in the above-described manner to the central exchange operator's station, thereby to cause the operation of the drop 466 and to signal the central exchange operator that a call on the trunk line 18 awaits attention.

The operator may thereupon insert the plug associated with the operator's telephone in the 75

5 jack 465 to establish a talking connection with the calling subscriber and to initiate, through the resulting sequential operation of the relays 420, 430 and 440, in the order named, the conditioning of the rotary stepping switch 401 to be responsive to impulses transmitted from the impulsing device 467. The manner in which the enumerated relays operate is described in a previous portion of the specification and need not 10 be repeated. Following receipt of the information concerning the party desired by the calling subscriber, the calling subscriber hangs up and the central exchange operator actuates the impulsing device 467 to cause the automatic switching equipment associated with the trunk lines 14 and 18 to connect the called subscriber's line to the first of these trunk lines. Thus, the digit 1 is the first digit dialed, causing one impulse to be transmitted to interrupt only once the previously-traced circuit for energizing the relay 420. When this relay restores, at the beginning of the impulse, it completes the previously prepared energizing circuit for the rotary magnet 460 and the slow-to-release relay 450. The relay 450, at its armature 451 and associated contact 452, interrupts the circuit for energizing the relay 470 and, at its armature 453, prepares an obvious circuit for energizing the relay 485. At the beginning of the impulse, the rotary magnet 460 steps the wipers 428 and 429 of the switch 401 to a position corresponding to the trunk line 14, or into engagement with the respective first contacts of the two contact sets 478 and 479. The off-normal springs 488 and 489 are also 25 closed during this stepping operation, so that, when the relay 450 restores after an interval following the single impulse, an obvious circuit is completed at the armature 451 for energizing the relay 470. Restoration of the relay 450 also 30 interrupts the previously prepared circuit for causing operation of the relay 485.

When the relay 470 operates in response to its energization in the manner described above, it closes, at its armature 472, a locking circuit for itself extending to ground at the operated armature 444 of the relay 440 and, at its armature 471, prepares the circuit for energizing the relay 485, this latter circuit being held open at the restored armature 453 of the relay 450. At its armature 476, the relay 470, upon operating, prepares the circuit for energizing the release magnet 462, this circuit being held open at the operated armature 445 of the relay 440. At its armature 477, the relay 470 interrupts a point in the operating circuit for the rotary magnet 460 thereby to prevent the switch 401 from responding to further impulses dialed at the impulsing device 467. In addition, the relay 470, at its armatures 473 and 474, completes, respectively, an energizing circuit 45 for the relay 490 and the second branch of the secondary circuit for the line relay 340. The first of these two circuits extends from ground at the armature 444 by way of the armatures 473 and 483, the wiper 428 and the associated first contact of the contact level 478, over the conductor 418 and through the winding of the relay 490 to battery. The second branch of the secondary circuit for the line relay 340 extends from ground at the operated armature 445 by way of the armature 474, the wiper 429 and the first contact of the contact level 479, and the conductor 414 to the upper terminal of the upper winding of relay 340. The closure of the last-mentioned circuit is of no effect at this time, since a multiple circuit to ground is already

closed at the armature 341 and associated contact 342 of the relay 340.

In response to the completion of the above-traced energizing circuit, the relay 490 operates and, at its armature 491, connects battery to the conductor 50, which conductor is connected by way of the trunk line conductor 30 and the lower repeater winding 218 to the ungrounded terminal of the line relay 290. Battery is extended to the conductor 50 over a path comprising the resistor 500, the armature 438 and associated contact 439 of the operated relay 430, the armature 421 and associated contact 422 of the operated relay 420, and the armature 491 and its associated armature 492. Operation of the relay 490 also disconnects the line conductor 50 from the link line conductor 27 at the armature 492. Thus, an impulsive circuit is completed for the line relay 290 included in the suboffice 11.

The equipment associated with the trunk line 18 is now in condition for transmitting further digits of impulses to the automatic switching equipment located in the suboffice 11 and associated with the suboffice trunk line 14. Moreover, the completion of the above-traced energizing circuit for the line relay 290 causes this relay to operate and initiate the conditioning of the automatic switching equipment associated with the trunk line 14 to be responsive to additional transmitted impulses. Thus, when the line relay 290 is energized over the above-traced circuit, it operates and, at its upper contact 291, completes the circuit for energizing the slow-to-release relay 280. The latter relay operates and, at its armature 281, closes a shunt path around the armature 271, at its armature 282, completes the circuit for the slow-to-release holding relay 270, and at its armature 283 prepares a circuit for energizing the relays 250 and 230 in parallel.

When the hold relay 270 operates, it opens, at its armature 271, the original operating circuit for the relay 200 and the secondary circuit of the line relay 120, this operation occurring only after the armature 281 has placed a shunt around the armature 271. The relay 270 also opens, at its armature 273, the previously completed energizing circuit for the timing means comprising the thermal relay 294, thereby arresting the operation of this relay. In addition, the relay 270 interrupts, at its armature 274 and the lower associated contact, the previously completed energizing circuit for the time relay 205 and, at this same armature and the associated upper contact, applies multiple ground to the conductor 105. At its armature 275, the hold relay 270 also prepares a path for energizing the secondary circuit of the line relay associated with the called subscriber's line. With the system in this condition, the automatic equipment associated with the trunk line 14 is in condition to respond to additional series of impulses transmitted from the impulsive device 467 at the central exchange operator's station.

The central exchange operator now actuates this device in accordance with the digits in the number corresponding to the called telephone or, in the present instance, in accordance with the digits 1 and 2, since the line 43' is the second line in the first group of ten lines and, consequently, the telephone number of the called subscriber is No. 112. In response to the operation of the dial of the impulsive device 467 in accordance with the second digit 1 and on the return of the dial to normal, the impulse springs 478' and 479' are momentarily opened once to inter-

rupt the energizing circuit of the line relay 420. At its armature 423, this relay closes the energizing circuit for the slow-to-release relay 450, the circuit to the rotary magnet 480 now being interrupted at the armature 471 of the relay 470. The relay 450 operates and, at its armature 453, completes the previously prepared energizing circuit for the relay 485, causing the latter relay to operate and, at its armature 486, to short-circuit, in an obvious manner, the winding of the relay 480.

In response to the restoration of the relay 420 during the dialing of the digit 1, battery is removed, at the armature 421, from the conductor 50 connected to the trunk line conductor 30 and thus the previously-traced energizing circuit for the line relay 290 is interrupted. When this relay falls back, it completes a circuit for energizing the relays 230 and 250 in multiple, this circuit extending from ground by way of the armature 291, the contact 292, the armature 283, the armature 242 and associated contact 244, where the circuit divides, one path going through the winding of the relay 230 to battery and the other path extending by way of the armature 241 and through the winding of the relay 250 to battery. The relay 230, upon operating, at its armature 232, opens a point in the circuit for energizing the operating magnet 212 and, at its armature 231, prepares a new operating circuit for itself in case the digit dialed comprises more than one impulse. The relay 250, upon operating, at its armature 251, short-circuits the relay 240 and prepares a circuit for energizing itself and the relay 240 in series. The short-circuiting path noted extends from ground by way of the armature 273 and its associated upper contact, the armature 251, the winding of relay 240, the armature 241 and by way of the armature 242 or the armature 231, the armature 283 and the armature 291 to ground.

When the second digit comprising one transmitted impulse is terminated, the contacts 478' and 478' of the impulsing device 467 again close to cause the reenergization and operation of the relay 420. This relay, at its armature 423, interrupts the circuit for energizing the slow-to-release relay 450 and again completes the circuit for the relay 430. It will be understood that the latter relay does not restore during impulsing due to its slow-to-release characteristic. After an interval, the relay 450 restores to open, at its armature 453, the original energizing circuit for the relay 485 and remove the shunt from around the winding of the relay 480. Thus, the relay 480 energizes in series with the relay 485 to prepare, at its armature 481 and associated contact 484, a circuit for energizing the relay 485', this circuit being held open at the restored armature 453 of the relay 450.

While the above-described operations are taking place, the armature 421 is closed to its associated contact 422, immediately upon the re-operation of the relay 420, thus connecting battery by way of the resistor 500 and the armature 491 to the conductor 50 to complete the previously-traced energizing circuit for the relay 290. When the relay 290 reoperates, in response to the completion of its energizing circuit in the above-described manner, it removes, at its armature 291, the short circuit from around the relay 240. The latter relay is now energized in series with the relay 250 over a circuit extending from ground at the armature 273 by way of the armature 251 and through the windings of the

relays 240 and 250 in series to battery. At its armature 242 and associated contact 243, the relay 240 prepares a point in the circuit for energizing the relay 260. At its armature 241, it opens a point in the original circuit for energizing the relay 260 and, at its armature 245, it prepares a point in the circuit for energizing the operating magnet 212 of the minor switch 225 and the slow-to-release relay 210 in parallel. In case the called subscriber's line were included in the second group of lines associated with the contact set 227, so that the second digit would necessarily comprise two impulses, the slow-to-release relay 230 would be maintained in its operated position during the second impulse to complete a circuit for the relay 260 by way of the armature 231 upon a second de-energization of the line relay 290. In the present case, however, since the second digit dialed is 1 and the line relay 290 is not de-energized a second time, the relay 260 is not at this time energized, and the relay 230 restores after an interval. The latter relay, upon restoring, at its armature 232, prepares a further point in the circuit for energizing the operating magnet 212. At its armature 231 the relay 230 opens a point in the circuit for energizing the relay 260 so that the latter relay will not be affected by the impulses of the third digit dialed at the operator's station. The automatic switching equipment associated respectively with the trunk line 18 and the trunk line 14 is now in condition to respond to the dialing of the third digit, which digit, in the present instance, is 2.

In response to the dialing of this digit, the relay 420 is again de-energized during each impulse and completes, at its armature 423, the energizing circuit for the relay 480, which relay again operates to complete, at its armature 483, a circuit for energizing the relay 485', this circuit extending from ground at the armature 453 by way of the armatures 481 and 481' and through the winding of the relay 485' to battery. When the relay 485' operates, it completes, at its armature 486', a path for short-circuiting the winding of the relay 480', this path extending from ground at the armature 453 by way of the armatures 481 and 481', the winding of the relay 480' and the armature 486' back to ground at the armature 444 of the energized relay 440.

Before proceeding with the description of the operation of the automatic switching equipment associated with the trunk line 14 in response to the de-energization of the line relay 290 during the impulses of the third digit, it is pointed out that the relay 450, due to its slow-to-release characteristic, remains operated during the transmission of impulses comprising digits greater than 1 and holds, at its armature 453, the shunt across the winding of the relay 480' so that the relay 490 is retained in its operated position. Hence, the conductor 50 is connected by way of the armature 491 to battery for a period during each succeeding impulse and corresponding to the energized condition of the relay 420 when the armature 421 is closed to its associated contact 422. In this way, the energizing circuit for the line relay 290 is alternately interrupted and completed during each impulse of any third digit greater than 1.

Returning now to the operation of the apparatus associated with the trunk line 14, when the third digit is dialed, and upon the first restoration of the line relay 290 in the above-described manner, there is completed, at the armature 291

5 An energizing circuit for the operating magnet 212, this circuit extending from ground by way of the armature 291, the contact 293, the armature 283, the armature 245, the armature 232 and 10 through the winding of the operating magnet 212 to battery. A branch from this circuit extends 15 through the winding of the slow-to-release relay 210, which relay operates and, at its armature 211, disconnects the switch wipers 213 and 214 20 from ground at the armature 275.

10 In response to the energization of its operating magnet 212, the minor switch 225 steps its wipers 213 and 215 into a position corresponding to the first subscriber's line of the first and second 15 groups or onto the respective first contacts of the two contact sets 226 and 227. Simultaneously with such stepping operation, the off-normal contacts 216 are closed to prepare a circuit for energizing the release magnet 215. At the conclusion 20 of the first impulse of the third digit when the relay 290 restores to interrupt the circuit for the magnet 212, this magnet de-energizes to condition the switch 225 to take a second step. The wipers 213 and 214 are thus stepped during each succeeding 25 impulse of the third digit at the rate of one step for each impulse. In the present case wherein the called line is the second line of the first group and the final digit comprises two impulses, the wipers 213 and 214 will be stepped 30 to their respective second off-normal positions or into engagement with the respective associated second contacts of the contact sets 226 and 227.

35 At the end of the third digit, when the interrupting springs 478' and 479' of the impulse device 461 are again closed to complete the energizing circuit for the relay 420, this relay reoperates to interrupt, at its armature 423, the circuit holding the relay 450 operated. When the latter relay falls back, in response to its de-energization, 40 it opens, at its armature 453, the shunt from around the winding of the relay 480', permitting this relay to operate in series with the relay 485' to interrupt, at its armature 483, the energizing 45 circuit for the relay 490. The latter relay restores to connect the line conductor 50 to the line conductor 27 and thereby substitute battery from the impedance element 499' for battery from the resistor 500. Before the last-described sequence of 50 operations is completed and immediately upon the reenergization of the relay 420, the energizing circuit for the line relay 290 is completed at the armature 421 so that this relay is in its operated condition when holding battery through the impedance 499' is substituted for operating battery 55 through the resistor 500.

55 The line relay 290, following its reenergization, reoperates to open the previously-traced energizing circuit for the relay 210 and the operating magnet 212 of the minor switch 225. At its armature 211, the relay 210 completes the secondary circuit for the line relay 110 associated with the called line 43', this circuit extending from ground by way of the armature 275, the armature 211, the armature 222, the wiper 213 in engagement with its second bank contact, the conductor 106, the upper winding of the line relay 110, the conductor 104, the armature 281 and through the winding of the relay 200 to battery. 60 In response to the completion of its secondary circuit, as above described, the relay 110 operates and completes, at its armature 113, a locking circuit for itself, which circuit comprises this armature, the upper winding of the relay 110, the conductor 104, the armature 281, the winding of the 65 relay 200 and battery. When the line relay 110

operates it connects, at its armatures 111 and 112, the subscriber's line conductors 182 and 183 of the line 43' to the link line conductors 102 and 103, respectively. It will now be seen that the line relays 110 and 120 are locked in their respective operated positions to connect the two subscribers' lines 42' and 43' to the conductors of the link line 115.

10 In order to notify the calling and called parties that the connection is completed, the central exchange operator now applies ringing current through the jack 465 and the repeaters 446 and 20, to the link line conductors 26 and 27 to transmit such current by way of the trunk line 14, the repeater 209, the link line 115 and the two subscribers' lines 42' and 43', to the respective bells or signal devices at the calling and called substations. In case more than one substation is connected to the called line 43', code ringing may be used to signal the desired substation. The 20 operation of the signal devices indicates to the calling and called parties that a connection is established, following which they may remove their receivers and converse as desired.

25 Before describing the release of the connection and in order to complete the description of the operation, it will be assumed that the called line is included in the second group of ten lines, or the group of lines having line relays comprising 30 secondary energizing circuits including the respective contacts of the contact set 221. Thus, assume that it is desired to call the substation F on the line 44, which line has associated therewith the line relay 140 whose secondary circuit includes a branch extending from battery on the 35 conductor 104 by way of the first contact of the contact set 227 and ultimately to ground at the armature 275. To complete this circuit it is necessary that the armature 222 of the relay 220 be operated. Energization of the relay 220 is 40 obtained by the operator's dialing a second digit of two impulses instead of one impulse as was the case for the selection of the lines in the first group of ten lines. It will be remembered from the foregoing description that at the end of the 45 first impulse of the second digit the two relays 250 and 240 are energized in series from ground at the operated armature 273 and that the relay 230, due to its slow-to-release characteristic, is maintained 50 operated. With the three relays 50 noted in their energized condition, a circuit is prepared for energizing the relay 260, which circuit extends from the contact 293 by way of the operated armatures 283, 231 and 242, the contact 243, the restored armature 221 and 55 through the winding of the relay 260 to battery. It will be observed that the branch of this circuit extending to the common terminals of the relays 250 and 240 is interrupted at the operated armature 241 and, hence, these relays are not affected 60 by the second impulse of the second digit. At the beginning of the second impulse of the second digit when the line relay 290 again restores, the above-traced circuit for energizing the relay 260 is completed at the armature 291. The relay 260 65 is completed at the armature 291. The relay 260 upon operating short-circuits at its armature 261 the winding of the relay 220 and prepares a circuit for energizing the relays 220 and 260 in series. At the conclusion of the second impulse of the second digit when the line relay 290 again 70 operates, the short circuit for the winding of the relay 220 is opened at the armature 291 and the two relays 260 and 220 are energized in series in a circuit extending from ground at the operated armature 273 by way of the operated armature 75

261 and the windings of the two relays noted to battery. The relay 220 upon operating interrupts, at its armature 221, the original operating circuit for the relay 260 and, at its armature 222, 5 prepares a circuit for energizing the secondary circuit of the line relay associated with the selected subscriber's line included in the second group of ten lines. Shortly following the end of the second digit the relay 230 restores to prepare, 10 at its armature 232 the above-mentioned circuit for energizing the rotary magnet 212 and the slow-to-release relay 210 in parallel. The operations which occur in response to the impulses comprising the third digit dialed at the central exchange operator's station are exactly the same as are set forth above. In the present assumed case wherein the called line 44 corresponds to the first off-normal position of the switch 225, this third digit will comprise a single impulse so 15 that at the conclusion thereof the wiper 214 will stand in engagement with the first contact of the contact set 221. Thereafter, and when the slow-to-release relay 210 restores shortly following the end of the third digit, the secondary circuit for the line relay 140 is completed at the armature 211. This circuit extends from ground at the armature 275 by way of the armatures 211 and 222, the wiper 214 and its associated first contact, the upper winding of the relay 140, the conductor 20 104, the armature 281 and the winding of the relay 200 to battery. The relay 140 operates to complete, at its armature 143, an obvious locking circuit for itself and to connect, at its armatures 141 and 142, the conductors of the called line 44 to the conductors of the link line 115. Thus, a 25 connection is established between the calling and called parties. From the foregoing description it will be apparent that in the event a connection is desired to a line in the first group of ten subscribers lines terminating at the suboffice 11, the second digit dialed at the central exchange operator's telephone will necessarily comprise a single impulse, whereas if the called line is included in the second group of ten lines the second digit will necessarily comprise two impulses. 30

Release of the connection

As pointed out above, the release of the connection established in the manner described above as well as the setting up of the connection, 35 is under the control of the operator in the central exchange. Thus, when the conversation is terminated, either the calling or the called party may signal the operator that the connection is no longer desired by ringing off to transmit ringing current over the trunk line 14 and the trunk line 18 to the drop 466 at the central exchange operator's station, causing the operation of this drop. The operator then initiates the release of the connection by removing the plug associated with the operator's telephone from the jack 465, thereby 40 interrupting at the contact 464 the previously-traced circuit for energizing the relay 420. This relay restores and interrupts, at its armature 423, the circuit holding the relay 430 operated and 45 closes, at the contact 425, a circuit for energizing the relay 450. When the relay 420 restores, it also opens, at its armature 421, a point in the original energizing circuit for the line relay 290. The latter relay is at this time, however, held 50 operated from battery at the impedance element 499'. The relay 450, upon being energized, again establishes the short circuit around the winding of the relay 480', permitting this relay to restore to cause the operation of the relay 480, which

latter relay operates to disconnect, at its armature 491, the line conductor 50 from the line conductor 27 and thereby interrupt the holding circuit for the line relay 290. The operation of the relay 450 in response to restoration of the relay 420 is, however, only momentary, since the relay 430 restores shortly after the relay 420 falls back and opens, at its armature 434, the circuit for energizing the relay 450, thereby to initiate the reoperation of the relay 480' and the interruption 10 of the energizing circuit for the relay 480. When the latter relay falls back, the line relay 290 is again energized from battery at the impedance element 499'. 15

When the relay 430 restores, it also interrupts, 20 at its armature 431 and associated contact 433, the circuit holding the relay 440 operated and, at its armature 436 and associated contact 437, opens the shunt around the armature 443, thereby to interrupt the previously-traced secondary circuit holding the line relay 340 and the relay 480 operated. At its armature 438, the relay 430 also opens a further point in the original energizing circuit for the line relay 290. When the relay 400 falls back, it interrupts, at its armature 403, 25 the multiple circuit holding the common cut-off relay 350 operated, and opens, at its armatures 401 and 405, respectively, a point in the circuit for energizing the tone relay 410 and the momentarily recompleted energizing circuit for the 30 thermal relay 418.

When the relay 440 restores, it opens, at its armature 442, the circuit including the impedance element 499' holding the line relay 290 energized. At its armature 441 and associated lower 35 contact, the relay 440 opens the circuit for the cut-off relay 350, permitting this relay to restore, and interrupt, at its armature 351, the circuit holding the cut-off relay 360 operated. It will be understood in view of the previous 40 description that the restoration of the relay 350 to remove, at the armature 353 and its associated contact 355, battery from the lower conductor 32 of the trunk line 15, leading to the suboffice 12, initiates the restoration of the cut-off relays, 45 corresponding to the relays 130 and 160 in the suboffice 11, thereby to recomplete the primary circuits of the line relays associated with the subscribers' lines terminating at the office 12. The relay 360 upon restoring completes, at its associated armatures, the individual primary circuits 50 for the line relays respectively associated with the subscribers' lines such, for example, as the lines 33 and 34. Shortly before the restoration of the cut-off relay 350, the line relay 340 restores to open, at its armature 341, a further point in its secondary circuit, to complete, at its armature 345, a point in its primary circuit and to interrupt, at its armature 343, the circuit holding the line relay 380 operated. The relay 380 55 restores and, at its armature 381, disconnects the trunk line conductor 29 from the link line conductor 26 and reconnects charging battery at the contact 382 to the trunk line conductor 29. The relay 380, at its armature 384, also disconnects 60 the trunk line conductor 30 from the link line conductor 50 and prepares a point in the primary circuit for the line relay 340, this latter circuit, as well as the corresponding circuit of the relay 330 being completed upon the restoration of the relay 350 to disconnect its armatures 353 and 356 from battery at the respective associated contacts 355 and 358, and to reconnect these armatures to their respective associated contacts 354 and 357. Since the relay 380 restores before the cut-off 65 70 75 80 85 90 95 100

relay 350 falls back, a holding circuit extending from battery at the resistor 336 and by way of the armature springs 356, 385 and 386 is momentarily completed for the line relay 290 included in equipment of the suboffice 11. This holding circuit is interrupted upon the sequential restoration of the relays 440 and 350, permitting the line relay 290 to restore to initiate the restoration of the switching equipment associated with the trunk line 14 in the suboffice 11. At this point, 10 all of the line relay equipment associated with the lines illustrated in Figure 4 is restored to normal.

Returning now to the operations which occur following the interruption of the circuit holding the relay 440 energized, it will be seen that, after an interval, this relay restores to disconnect, at its armature 442, holding battery for the line relay 290 and to prepare, at its armature 441, the circuit for energizing the tone relay 410, this latter circuit being held open at the armature 401 of the restored relay 400. The relay 440, upon restoring, also prepares, at its armature 443, a point in the common portion of the secondary energizing circuits for the line relays associated with the lines accessible to the link line 28, namely, the relays 310, 320, 330, 340, etc. It is pointed out, however, that before the armature 443 falls back, the armature 445 is moved away from its associated upper contact, so that the latter armature 445 interrupts the previously-traced branch of the secondary circuit for the relay 340 comprising the multiple path shunting the armature 341 and extending from ground at the armature 445 by way of the wiper 429 and the conductor 414. Thus, both paths extending to the upper terminal of the upper winding of the relay 340 are open at the time the relay 440 completely restores its armature 443 to complete the path extending from battery at the relay 400 to the lower terminal of this winding.

Restoration of the armature 445 completes, at its associated lower contact, the previously prepared energizing circuit for the release magnet 462, causing this magnet to operate and permit the switch 407 to restore its wipers 428 and 429 to their respective normal positions and to open the off-normal springs 488 and 489.

At its armature 444, the hold relay 440, upon restoring, interrupts the holding circuits for the relays 470, 480, 485 and 485', permitting these four relays to restore. When the relay 470 falls back, it opens, at its armature 476, the circuit for energizing the release magnet 462. It will be apparent from the foregoing description that the automatic switching equipment associated with the trunk line 18 and the line relay equipment associated with the respective subscribers' and suboffice lines illustrated in Figure 4 are now restored to the condition which prevailed at the outset when all of these lines were idle.

Turning now to the operations which occur upon the restoration of the line relay 290 associated with the trunk line 14, this relay initiates the restoration to normal of the automatic switch 225 and the control equipment associated therewith. Thus, at its armature 291, the relay 290, upon restoring, interrupts the circuit holding the series relay 280 operated. After an interval, the slow-to-release relay 280 restores and, at its armature 281, opens the circuit holding the relays 280, 110 and 120 operated. At its armature 282, the relay 280 opens the circuit of the hold relay 270 and, at its armature 283, opens a 75 point in the circuit for the operating magnet 212.

The relay 200, upon de-energizing, at its armature 201, disconnects one of the multiple grounds from the conductor 105 included in the circuit for holding the cut-off relay 130 operated, at its armature 202, opens a further point in the circuit 5 of the thermal relay 294, at its armature 203, opens a point in the circuit of the tone relay 205 and, at its armature 204, prepares a point in the charging circuit for the common battery of the suboffice 11. The line relays 110 and 120 restore 10 simultaneously with the relay 200, to disconnect, at their armatures 111, 112 and 121, 122, respectively, the subscribers' lines 42' and 43' from the trunk line 14. At their respective armatures 112 and 122 and the respective associated lower contacts, the line relays 110 and 120 prepare points 15 in their primary circuits which circuits are, however, still maintained open due to the energized condition of the common cut-off relay 130. From the foregoing description, it will be seen that 20 the line relays 110 and 120 are de-energized in response to the restoration of the relay 420. It will further be observed that the subscribers at the substations D and E can not energize the line relays individually associated with their respective 25 lines to initiate a call until such time as the apparatus associated with the trunk line 14 is fully released.

Shortly after the restoration of the relay 280, the hold relay 270 falls back and, at its armature 271, prepares the secondary circuit for the subscribers' line relays, which circuit includes the winding of the relay 200. At its armature 274, the hold relay 270 removes ground from the conductor 105 to interrupt the circuit holding 35 the common cut-off relay 130 operated. At its armature 273, the relay 270 prepares a point in the circuit for energizing the thermal relay 294, and, at its armature 273 and associated upper contact, the relay 270 opens a point in the common branch of the holding circuits for the relays 220, 240, 250 and 260 causing their de-energization, if energized. At its armature 272, the relay 270 completes a path including the upper winding of the tone relay 205 for transmitting waiting 40 tone current to a calling subscriber. At its armature 274, the relay 270 prepares a point in the circuit to the tone relay 205 and, at its armature 275, this relay disconnects ground from the minor switch wiper 213 and completes the circuit 45 for energizing the release magnet 215 of the minor switch 225. The switch 225 responds by restoring its wipers 213 and 214 to their respective normal positions and opening the off-normal springs 216. The off-normal springs open, in turn, the circuit for energizing the release magnet 215. It is pointed out that the secondary circuits for the restored line relays 110 and 120 and including the winding of the relay 200 are opened at the armature 275 of the relay 270 before the 50 armature 271 engages its associated contact. Thus, these relays are prevented from being 55 momentarily reoperated.

The cut-off relay 130, upon de-energizing, at its respective armatures 131, 132, 133, etc., completes the primary circuits for the line relays 110, 120, etc., individually associated with the respective subscribers' lines of the first group, thereby to condition these relays to be responsive to calls initiated on their respective associated lines. At its armature 134, the relay 130 65 interrupts the operating circuit for the cut-off relay 160 permitting this relay to restore and complete at its armatures 161, 162, 163, etc., the primary circuits of the relays 140, 150, etc., in- 70 75

cluded in the second group of ten subscribers' lines terminating at the suboffice 11. At its armature 164, the relay 160, upon restoring, connects the negative terminal of the suboffice common battery by way of the conductor 101, the upper right-hand winding 217 of the repeater 209 and over the trunk conductor 29 to the negative terminal of the common battery at the tandem office 13, thereby to complete the previously described charging circuit for maintaining the suboffice common battery fully charged. It should possibly be mentioned that, when either the common cut-off relay 130 or the relay 200 is operated, direct negative battery is disconnected from the conductor 101, so that the trunk line 14 is clear.

The system is now in the normal condition which prevailed before the connection, as described above, was established.

20 *Reverting call to a suboffice subscriber's substation*

In order to make a reverting call or a call in which one of the suboffice subscribers desired to converse with another subscriber on the same line, the calling subscriber initiates the call and signals the central exchange operator in the exact manner just described, after which the calling party replaces his receiver and the operator rings back over the two tandem connected trunk lines 18 and 14 and the interconnecting link lines, without dialing, to signal the desired subscriber on the calling line by transmitting the proper code ring of the called party. As pointed out above, such operation is not necessary where the calling party is familiar with the code ring of the desired party on the same line, since he may then ring directly the desired party. Such code ringing, however, ties up for a short interval the automatic equipment associated with the trunk lines 14 and 18 but this equipment is released by the operation of the timing means comprising the two thermal relays 294 and 413 in the manner previously described. If, during a reverting call, the operator assists in completing the call, she may release the established connection to the central exchange operator's station immediately upon transmitting the coded ring to the desired party by removing the plug associated with her telephone set from the jack 465. This operation on the part of the operator initiates the release of the automatic equipment associated with the trunk lines 18 and 14 in the exact manner set forth above.

55 *A call from one suboffice subscriber's line to a subscriber's line terminating at another suboffice*

If a subscriber at a substation such, for example, as the substation D connected to a subscriber's line terminating at one of the suboffices desires a talking connection with a subscriber's substation connected to one of the lines terminating at another suboffice, as for example, the suboffice 12, such a connection may be set up by operations almost identical with those performed in establishing a connection to a line terminating at the same suboffice. Thus, the operation of the automatic equipment to establish a connection to the operator's station and to signal the operator thereat are identical with those described above. In case the connection is to be extended to a subscriber's line in the suboffice 12, the operator dials the digit corresponding to this suboffice, namely the digit 2. In response to such dialing, the automatic switch 407

steps its wiper, 428 and 429 to the position corresponding to the trunk line 18 or into engagement with the respective second contacts of the contact sets 478 and 479. This causes the seizure of the trunk line 18 and the conditioning of the automatic equipment associated with this line in the suboffice 12 to be responsive to further impulses constituting additional digits dialed at the impulsing device 467. The method by which such a connection may be released is identical with that described above and for this reason need not be repeated.

A call from a suboffice subscriber's line to a subscriber's line terminating at the tandem office

In the event a subscriber on a line terminating at one of the suboffices desires to converse with a party whose line terminates at the tandem office, a connection is first established from the calling line to the central exchange operator's telephone in the manner described above in connection with calls from one suboffice subscriber's line to a line terminating at the same suboffice. Following this, the operator completes the connection by dialing a single digit to cause the automatic switch 407 to step its wipers to a position corresponding to the called subscriber's line terminating at the tandem office. As a consequence of the operation of the switch 407, the secondary circuit of the line relay associated with the called line is completed, causing this line relay to operate and complete the desired connection. The details of the operation of the automatic switching equipment associated with the trunk line 18 during such a dialing operation have previously been described in connection with a call from one tandem subscriber's line to another tandem subscriber's line and for that reason need not be repeated at this point. It is also believed that the method by which such a connection can be released will be obvious in view of the foregoing description and, consequently, in the interest of simplifying the description, a detailed analysis thereof is omitted.

It will also be apparent that the method by which a connection may be established from any one of the suboffice subscribers' lines to a line terminating at the central exchange is exactly the same, following the establishing of a connection to the central exchange operator's station, as that described in a preceding portion of the specification with reference to a call extended from a tandem office subscriber's line to a line terminating at the central exchange.

It will further be evident that a call may be extended from any line terminating at the central exchange to any one of the subscribers' lines terminating at the respective suboffices or the tandem office by the operator's first establishing a connection from the operator's telephone to the desired called party and subsequently establishing the desired connection between the calling and called parties in a manner well-known to those familiar with the practices followed in manual exchanges. In view of the foregoing description, the general method by which the automatic equipment associated with the trunk lines 18 and 14, respectively, operates to set up such a connection is believed to be obvious and for that reason is not described in detail herein. It is noted, however, that the instant the trunk line 18 is seized by the central exchange operator in the course of establishing such a connection, both of the common cut-off relays 350 and 360 associated with the line 18 are op-

erated to prevent the seizure of this line on incoming calls to the tandem office, and the common cut-off relays in the respective suboffices individually associated with the trunk lines 14 and 15 are operated to prevent calls from being routed over these lines to the central exchange. Thus, when the line relay 420 operates in response to the connection of the central exchange operator's telephone to the trunk line 18, this relay causes the sequential operation of the relays 430 and 440. The last-mentioned relay, at its armature 441 and associated lower contact, completes the circuit extending by way of the conductor 499 for energizing the common cut-off relay 350. As described previously, this relay completes, at its armature 351, circuit for energizing the common cut-off relay 360 and, at its armatures 353 and 356 and their respective associated contacts 354 and 357, interrupts the primary circuit for the line relays 330 and 340 respectively associated with the suboffice trunk lines 15 and 14. When the relay 360 operates, it opens the primary circuits for all of the line relays associated with the tandem office subscribers' lines such, for example, as the lines 33 and 34.

The common cut-off relay 350, upon operating, also initiates the operation of the common cut-off relays in the suboffice 11 and 12 respectively associated with the trunk lines 14 and 15. Thus, this relay, at its armature 356 and associated contact 358, connects battery to the lower trunk line conductor 38 to complete a previously-traced circuit for energizing the line relay 290. Operation of the relay 290 causes the sequential operation of the relays 280 and 270. The latter relay at its armature 274 completes the circuit for energizing the common cut-off relay 130, which relay in turn interrupts the primary circuits for the subscribers' line relays 110, 120, etc., individually associated with the lines of the first group of ten subscribers' lines, and completes, at its armature 134, the operating circuit for the relay 160. The relay 160 in turn interrupts the primary circuits for the line relays 140, etc., individually associated with the lines of the second group of ten subscribers' lines, all in the manner previously described. In this way the trunk line 18 is guarded against seizure in response to the initiation of a call on one of the subscribers' lines terminating at the tandem office or at one of the suboffices and no false signals are transmitted to calling subscribers on lines terminating at the suboffices.

While there has been described what is at present considered to be the preferred embodiment of the invention, it will be understood that various modifications may be made therein, and it is intended in the appended claims to cover all such modifications as fall within the true spirit and scope of the invention.

I claim:

1. In a telephone system, a central office, a tandem office and a plurality of suboffices, subscriber lines individually extending to each of said offices, trunk lines interconnecting said offices, an operator's station at said central office, means responsive to the initiation of a call on one of the subscribers' lines extending to said tandem office or to one of said suboffices for signaling an operator at said station and for establishing a talking connection between the calling line and said operator's station, impulsive means at said station, means included in said tandem office and responsive to impulses transmitted from said impulsive means back over the trunk line inter-

connecting said tandem and central offices for connecting the calling line to a subscriber's line extending to said tandem office or to one of the trunk lines extending to one of said suboffices, depending upon the line being called, and means in said one suboffice and responsive to additional impulses transmitted from said impulsive means back over the trunk line interconnecting said tandem office and said central office for connecting the calling line to the called subscriber's line in case the called subscriber's line extends to said one suboffice. 5 10

2. In a telephone system, a central office, a tandem office, and a suboffice, subscribers' lines individually extending to each of said offices, a trunk line connecting said tandem office and said suboffice, a central office trunk line connecting said tandem office and said central office, an operator's station at said central office, each of said tandem office subscribers' lines having associated therewith means responsive to the initiation of a call on the associated line to one of said suboffice subscribers' lines for connecting the calling subscriber's line to said central office trunk line to signal the operator at said station and to establish a talking connection between the calling subscriber's line and said operator's station, impulsive means at said station, means included in said tandem office and responsive to impulses transmitted from said means responsive to the operation of any one of said last-named means for rendering the other similar means inoperative to connect their respective associated lines to said central office trunk line in response to calls initiated on said respective associated lines, impulsive means back over said central office trunk line for connecting said calling line to the trunk line connecting said tandem office and said suboffice, and means in said suboffice and responsive to additional impulses transmitted from said impulsive means back over said central office trunk line and over said last-named trunk line for connecting said last-named trunk line to the called subscriber's line. 25 30 35 40

3. In a telephone system, a central office, a tandem office and a suboffice, subscribers' lines individually extending to each of said offices, a trunk line connecting said tandem office and said central office, a trunk line connecting said tandem office and said suboffice, an operator's station at said central office, each of said suboffice subscribers' lines having associated therewith means responsive to the initiation of a call on the associated line to a subscriber's line extending to said tandem office for establishing a connection between the calling subscriber's line through to said operator's station by way of said trunk lines and for signaling the operator, means responsive to the operation of any one of said last-named means for rendering the other similar means inoperative to connect their respective associated lines to said suboffice trunk line in response to calls initiated on said respective associated lines, impulsive means at said station, and means included in said tandem office and responsive to impulses transmitted by said impulsive means back over the trunk line extending between said tandem and central offices for establishing a connection between said calling line and the called subscriber's line. 45 50 55 60 65

4. In a telephone system, a central office, a tandem office and a plurality of suboffices, subscriber lines individually extending to each of said offices, trunk lines individually connecting each of said suboffices with said tandem office, a 70 75

central office trunk line connecting said tandem office with said central office, an operator's station at said central office, each of said suboffice trunk lines and tandem office subscribers' lines 5 having associated therewith means responsive to a call initiated on the associated line for connecting the associated line to said central office trunk line to establish a connection between the calling subscriber's line and said operator's station, means responsive to the operation of any 10 one of said last-named means for rendering the other similar means inoperative to connect their respective associated lines to said central office trunk line in response to calls initiated on said 15 respective associated lines, impulsive means at said station, and means including means in said tandem office and means in each of said suboffices, each responsive to impulses transmitted back over said central office trunk line, for establishing a connection between said calling line and a called subscriber's line extending to said 20 tandem office or to one of said suboffices, depending upon the line called.

5. In a telephone system, a central office, a tandem office and a plurality of suboffices, subscribers' lines individually extending to each of said offices, trunk lines individually connecting each of said suboffices with said tandem office, a central office trunk line connecting said tandem office with said central office, an operator's station at said central office, each of said suboffice 25 trunk lines and tandem office subscribers' lines having associated therewith at said tandem office a line relay responsive to a call initiated on the associated line for connecting the associated line to said central office trunk line to establish a connection between the calling subscriber's line and said operator's station, means responsive to the operation of any one of said line 30 relays for rendering the other similar relays inoperative to connect their associated lines to said central office trunk line in response to calls initiated on said respective associated lines, impulsive means at said station, and means including means in said tandem office and means in each 35 of said suboffices, each responsive to impulses transmitted back over said central office trunk line, for establishing a connection between said calling line and a called subscriber's line extending to said tandem office or to one of said suboffices, depending upon the line called.

6. In a telephone system, a tandem office, subscribers' lines extending to said office, suboffice trunk lines extending to said office, each of said subscribers' and trunk lines having associated therewith a line relay for completing and maintaining connections, a central office trunk line, means responsive to the initiation of a call on any one of said suboffice trunk lines or subscribers' lines for causing the line relay associated with the calling line to connect the calling line to said central office trunk line, and means responsive to the operation of one of said line relays for preventing all of the other line relays 55 from operating in response to the initiation of calls on the lines respectively associated therewith.

7. In a telephone system, a tandem office, subscribers' lines extending to said office, suboffice 70 trunk lines extending to said office, each of said subscribers' and trunk lines having associated therewith a line relay for completing and maintaining connections, an energizing circuit for each of said line relays including the conductors 75 of the associated line, a central office trunk line,

means responsive to the initiation of a call on any one of said suboffice trunk lines or subscribers' lines and operable only when said central office trunk line is idle for causing the line relay associated with the calling line to connect the associated line to said central office trunk line, and means comprising a cut-off relay having contacts individually included in the energizing circuits of said subscribers' line relays and responsive to operation of the line relay of said 10 calling line for interrupting the energizing circuits of all of the other subscribers' line relays.

8. In a telephone system, a tandem office, subscribers' lines extending to said office, suboffice trunk lines extending to said office, each of said subscribers' and trunk lines having associated therewith a line relay including a primary circuit and a secondary circuit so connected and arranged that operation of each relay is initiated by energization of its primary circuit following 15 which its secondary circuit is completed to complete the operation of the corresponding relay and to hold it in its operated position independently of the primary circuit, a central office trunk line extending to said tandem office, each 20 of said relays being adapted when fully operated, to complete and maintain a connection between the associated line and said central office trunk line, means responsive to the initiation of a call on any one of said suboffice trunk lines or subscribers' lines for energizing the primary circuit 25 of the line relay associated with the calling line, and means responsive to the operation of the line relay of said calling line for interrupting the primary energizing circuits of all of said line 30 relays.

9. In a telephone system, a tandem office, subscribers' lines extending to said office, suboffice trunk lines extending to said office, each of said subscribers' and trunk lines having associated therewith a line relay including a primary circuit and a secondary circuit so connected and arranged that operation of each relay is initiated by energization of its primary circuit, following 40 which its secondary circuit is completed to complete the operation of the relay and to hold it 45 operated independently of the primary energizing circuit, a central office trunk line extending to said tandem office, each of said relays being adapted, when fully operated, to complete and maintain a connection between the associated line and said central office trunk line, means responsive to the initiation of a call on any of said suboffice trunk lines or subscribers' lines for energizing the primary circuit of the line relay associated with the calling line, a cut-off relay 50 including contacts individually included in the primary circuits of the line relays associated with said suboffice trunk lines, said relay being operated in response to the operation of the line 55 relay associated with the calling line to interrupt the primary circuits of said suboffice trunk line relays, and a second cut-off relay operated in response to the operation of said first named 60 cut-off relay for interrupting the primary circuits of said subscribers' line relays.

10. In a telephone system, an office, a pair of lines extending to said office, a trunk line extending to said office, line relays individually associated with each of said pair of lines for connecting 70 the associated line to said trunk line, each of said relays including a primary circuit and a secondary circuit so connected and arranged that operation of each relay is initiated by energization of its primary circuit and completed by com- 75

- pletion of its secondary circuit, means operated during the initiation of a call on one of said pair of lines for energizing the primary circuit of the associated line relay, means responsive to the energization of said primary circuit for completing the secondary circuit of the corresponding line relay, and means responsive to the resulting operation of said corresponding line relay for interrupting the primary circuit of said other line relay.
11. In a telephone system, an office, a pair of lines extending to said office, a trunk line extending to said office, line relays individually associated with each of said pair of lines for connecting the associated line to said trunk line, each of said relays including a primary circuit and a secondary circuit so connected and arranged that operation of each relay is initiated by energization of its primary circuit and completed by completion of its secondary circuit, means operated during the initiation of a call on one of said pair of lines for energizing the primary circuit of the associated line relay, means responsive to the energization of said primary circuit for completing the secondary circuit of the corresponding relay, an additional relay operated in response to the resulting operation of said corresponding relay, means responsive to the operation of said additional relay for interrupting the primary circuit of the other line relay, and means also responsive to the operation of said additional relay for signaling over the calling line that said trunk line is idle.
12. In a telephone system, an office, a pair of lines extending to said office, a trunk line extending to said office, line relays individually associated with each of said pair of lines for connecting the associated line to said trunk line, an operator's telephone adapted to be connected to said trunk line, each of said relays including a primary circuit and a secondary circuit so connected and arranged that operation of each relay is initiated by energization of its primary circuit and completed by completion of its secondary circuit, means operated during the initiation of a call on one of said pair of lines for energizing the primary circuit of the associated line relay, means responsive to the energization of said primary circuit for completing the secondary circuit of the corresponding relay, timing means for causing the interruption of said completed secondary circuit in the event said operator's telephone is not connected to said trunk line within a predetermined time interval after the operation of said timing means is initiated, an additional relay operable simultaneously with the completion of said secondary circuit for initiating the operation of said timing means, means responsive to operation of said additional relay for interrupting the primary circuits of both of said line relays, and means also responsive to the operation of said additional relay for signaling over the calling line that said trunk line is idle.
13. In a telephone system, an office, a pair of lines extending to said office, a trunk line extending to said office, line relays individually associated with each of said pair of lines for connecting the associated line to said trunk line, an operator's telephone adapted to be connected to said trunk line, each of said relays including a primary circuit and a secondary circuit so connected and arranged that operation of each relay is initiated by energization of its primary circuit and completed by completion of its secondary circuit, means operated during the initiation of a call on one of said pair of lines for energizing the primary circuit of the associated line relay, means responsive to the energization of said primary circuit for completing the secondary circuit of the corresponding relay, timing means for causing the interruption of said completed secondary circuit in the event said operator's telephone is not connected to said trunk line within a predetermined time interval after the operation of said timing means is initiated, an additional relay operable simultaneously with the completion of said secondary circuit for initiating the operation of said timing means, means responsive to operation of said additional relay for interrupting the primary circuits of both of said line relays, and means also responsive to the operation of said additional relay for signaling over the calling line that said trunk line is idle.
14. In a telephone system, an office, a pair of lines extending to said office, line relays individually associated with each of said pair of lines for connecting the associated line to said trunk line, an operator's telephone adapted to be connected to said trunk line, each of said relays including a primary circuit and a secondary circuit so connected and arranged that operation of each relay is initiated by energization of its primary circuit and completed by completion of its secondary circuit, an additional relay having a winding common to the secondary circuits of said line relays, whereby said additional relay is operated simultaneously with the operation of either of said line relays, means operated during the initiation of a call on one of said pair of lines for energizing the primary circuit of the associated line relay, means responsive to the energization of said primary circuit for completing the secondary circuit of the corresponding relay, timing means for causing the interruption of said completed secondary circuit in the event said operator's telephone is not connected to said trunk line within a predetermined time interval after the operation of said timing means is initiated, said additional relay being operative to initiate the operation of said timing means, means responsive to operation of said additional relay for interrupting the primary circuits of both of said line relays, and means also responsive to the operation of said additional relay for signaling over the calling line that said trunk line is idle.
15. In a telephone system, a trunk line, an operator's telephone having access to said trunk line, a plurality of lines having access to said trunk line, timing means associated with said trunk line, means responsive to the connection of one of said plurality of lines to said trunk line for initiating the operation of said timing means, means responsive to the connection of said operator's telephone to said trunk line for arresting the operation of said timing means, and means including said timing means for disconnecting said one line from said trunk line in the event said operator's telephone is not connected to said trunk line within a predetermined time interval after said one line is connected to said trunk line.
16. In a telephone system, a trunk line, an operator's telephone having access to said trunk line, a plurality of lines having access to said trunk line, timing means associated with said trunk line, each of said plurality of lines having associated therewith a line relay responsive to the initiation of a call on the associated line for

- connecting the associated line to said trunk line, an additional relay operable simultaneously with the operation of any one of said line relays, means responsive to the operation of said additional relay for preventing others of said line relays from operating in response to calls initiated on their respective associated lines, timing means also responsive to the operation of said additional relay for causing restoration of the operated line relay 5
- 10 at the end of a predetermined time interval, and means responsive to the connection of said operator's telephone to said trunk line for arresting the operation of said timing means.
- 15 17. In a telephone system, a plurality of subscribers' lines, a line relay individual to each of said lines, an automatic switch operable to different positions individually corresponding to individual ones of said subscribers' lines, a primary circuit for each of said relays, each of said 10 circuits being adapted to be energized in response to the initiation of a call on the line associated with the corresponding relay, a secondary circuit for each of said relays, each of said secondary circuits being completed in response to the operation 15 of the corresponding relay when its primary circuit is energized, means responsive to the completion of the secondary circuit of any one of said relays for preventing the energization of any of said primary circuits, and means responsive to the 20 operation of said switch to a position corresponding to a called line for completing the secondary circuit of the relay associated with said called line to cause the operation of the last named relay and thereby establish a connection 25 between a calling line and said called line.
- 30 18. In a telephone system, a trunk line, an operator's telephone accessible to said trunk line, impulsing means at said operator's telephone, a plurality of lines accessible to said trunk line, a line relay individual to each of said plurality of lines, an automatic switch operable to different 35 positions individually corresponding to individual ones of said plurality of lines, a primary circuit for each of said relays, each of said circuits being adapted to be energized in response to the initiation of a call on the line associated with the corresponding relay, a secondary circuit for each of said relays, each of said secondary circuits being completed in response to the operation 40 of the corresponding relay when its primary circuit is energized, each of said relays being operable to connect its associated line to said trunk line when its secondary circuit is completed, means responsive to the connection of any one of said plurality of lines to said trunk line for preventing the energization of any of said primary circuits, means responsive to the operation 45 of said impulsing means for operating said switch to a predetermined position corresponding to a line being called, and means responsive to the operation of said switch to said predetermined position for completing the secondary circuit of the relay associated with the called line, thereby to establish a connection between said called line and a calling line.
- 55 19. In a telephone system, a central office, a suboffice, a tandem office, a central office trunk line connecting said central office and said tandem office, a group of lines accessible to said central office trunk line, a suboffice trunk line connecting 60 said tandem office and said suboffice and accessible to said central office trunk line, a group of lines accessible to said suboffice trunk line, an operator's telephone accessible to said central office trunk line, each of said second-named group of lines having associated therewith means responsive to the initiation of a call on the associated line for connecting the associated line to said central office trunk line, and means responsive to the operation of any one of said first-named group of lines to said central office trunk line for preventing any of said last named means from operating when calls are initiated on the lines respectively associated therewith.
- 65 20. In a telephone system, a central office, a suboffice, a tandem office, a central office trunk line connecting said central office and said tandem office, a group of lines accessible to said central office trunk line, a suboffice trunk line connecting 70 said tandem office and said suboffice and accessible to said central office trunk line, a group of lines accessible to said suboffice trunk line, a group of lines accessible to said central office trunk line, an operator's telephone accessible to said central office trunk line, each of the lines of said first and second-named groups of lines having associated therewith means responsive to the initiation of a call on the associated line for connecting the associated line to said central office trunk line, and means responsive to the connection of said operator's telephone to said central office trunk line for preventing any of said last-named means from operating when calls are initiated on the lines respectively associated therewith.
- 75 21. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, an operator's telephone accessible to said central office trunk line, means responsive to the connection of said operator's telephone to said central office trunk line for preventing any one of the lines of said first named group of lines from being connected to said central office trunk line in response to the initiation of a call on the said one of said first named group of lines, and means also responsive to the connection of said operator's telephone to said central office trunk line for preventing any one of said second named group of lines from being connected to said suboffice trunk line in response to the initiation of a call on the said one of said second named group of lines.
- 80 22. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, an operator's telephone accessible to said central office trunk line, each of said second-named group of lines having associated therewith means responsive to the initiation of a call on the associated line for connecting the associated line to said suboffice trunk line, and means responsive to the connection of said operator's telephone or any one of said first named group of lines to said central office trunk line for preventing any of said last named means from operating when calls are initiated on the lines respectively associated therewith.
- 85 23. In a telephone system, a central office, a suboffice, a tandem office, a central office trunk line connecting said central office and said tandem office, a group of lines accessible to said central office trunk line, a suboffice trunk line connecting 90

- 5 said tandem office and said suboffice and accessible to said central office trunk line, a group of lines accessible to said suboffice trunk line, an operator's telephone accessible to said central office trunk line, each of said second-named group 5 of lines having associated therewith means responsive to the initiation of a call on the associated line for connecting the associated line to said suboffice trunk line, means responsive to the 10 connection of said operator's telephone or any one of said first-named group of lines to said central office trunk line for preventing any of said last-named means from operating when calls are initiated on the lines respectively associated therewith, and automatic switching means for 15 connecting a called line of said second-named group of lines to said suboffice trunk line to establish a connection between said called line and a calling line.
- 20 24. In a telephone system, a plurality of subscribers' lines, a line relay individual to each line, an automatic switch for selecting called subscribers' lines, individual subscriber connections from said switch to corresponding line relays, a first operating circuit for each line relay including both talking conductors of the corresponding calling line completed responsive to the initiation of a call by a calling subscriber, a second operating circuit for each line relay including the corresponding called subscriber's individual switch connection completed by said switch in response to said switch selecting the called subscriber's line, a cut-off relay common to said lines operated in response to the operation of any line relay, and contacts on said common cut-off relay for controlling all said first operating circuits.
- 25 25. In a telephone system, a plurality of subscribers' lines, a line relay individual to each line, an automatic switch for selecting called subscribers' lines, individual subscriber connections from said switch to corresponding line relays, a first operating circuit for each line relay including both talking conductors of the corresponding calling line completed responsive to the initiation of a call by a calling subscriber, a second operating circuit for each line relay including the corresponding called subscriber's individual switch connection completed by said switch in response to said switch selecting the called subscriber's line, a cut-off relay common to said lines operated in response to the operation of any line relay, contacts on said common cut-off relay for controlling all said first operating circuits, a locking circuit for each line relay, and means in said switch for controlling said locking circuits.
- 30 26. In a telephone system, a plurality of subscribers' lines, a line relay individual to each line, a cut-off relay common to all said lines, an automatic switch for selecting called subscribers' lines, individual subscriber connections from said switch to corresponding line relays, a first operating circuit for each line relay including both talking conductors of the calling line and contacts on said common cut-off relay completed responsive to the initiation of a call by a calling subscriber, and a second operating circuit for each line relay completed over the called subscriber's individual switch connection by said switch in response to said switch selecting the called line.
- 35 27. In a telephone system, a plurality of subscribers' lines, a line relay individual to each line, an automatic switch for selecting called sub-
- scribers' lines, individual subscriber connections extending from said switch to corresponding line relays, an operating circuit for energizing each line relay including the corresponding called subscriber's individual switch connection completed by said switch in response to said switch selecting the called subscriber's line, a trunk line individual to said switch, and contacts on said line relays for directly connecting said subscribers' lines to said trunk line independent of said switch, each 10 of said line relays having an operating circuit energized in response to the initiation of a call on the associated subscribers' line, whereby said subscribers' lines are individually connected to said trunk line by their respective associated line 15 relays when calls are individually initiated thereon.
- 40 28. In a telephone system, a first exchange and a second exchange, a plurality of subscribers' lines terminating in the first exchange, a trunk line connecting said exchanges, an automatic switch in the first exchange individual to said trunk line, a line relay individual to a calling subscriber's line operated in response to such line initiating a call, contacts on said relay directly 20 connecting the calling line to said trunk line, means for operating said switch over the trunk line from the second exchange to select a called subscriber's line, a line relay individual to the called line operated in response to said selection, 25 contacts on the line relay of the called line for directly connecting said trunk line to the called line thereby connecting the calling and called lines to said trunk line for telephonic purposes, and means controlled over said trunk line from 30 the second exchange independent of the calling and called lines for maintaining said established connection by maintaining said line relays in 35 operated position.
- 45 29. In a telephone system, a first exchange and a second exchange, a plurality of subscribers' lines terminating in the first exchange, a trunk line connecting said exchange, a line relay individual to a calling subscriber's line operated in response to such line initiating a call, contacts 40 on said line relay directly connecting the calling line to said trunk line, means responsive to said connection for transmitting a waiting tone over said trunk line to the calling line until the call is answered at the second exchange, an automatic switch at the first exchange operated over said 45 trunk line from the second exchange for selecting a called subscriber's line, a line relay individual to the called line operated in response to said selection, contacts on the line relay directly 50 connecting said trunk line to the called line thereby connecting the calling and called lines to said trunk line, a locking circuit for said line relays effective on operation of said relays, and means in said first exchange controlled over said 55 trunk line from the second exchange for controlling said locking circuits to maintain or release said direct connections.
- 60 30. In a telephone system, a trunk line, a subscriber's line, a line relay for said subscriber's line, contacts on said relay completing an operating circuit for said relay including an operating winding bridged across the subscriber's line when such subscriber initiates a call and for disconnecting said operating winding from across 65 said subscriber's line when said relay operates, contacts on said relay for locking said relay over a locking winding when said relay operates, contacts on said relay for directly connecting said subscriber's line to said trunk line when said 70
- 75 75

- relay operates, and a circuit for operating said relay when said line is called including said locking winding.
31. In a telephone system, a first office, a second office, a trunk line connecting said offices, each of said offices including a common battery individual thereto for operating the apparatus therein, said batteries having their voltages so proportioned, and being so related to said trunk line, that the battery of said second office is charged from the battery of said first office, a plurality of subscribers' lines extending to said first office, each of said subscribers' lines having connected thereto at least one subscriber's substation of the local battery type and being accessible to a link line included in said trunk line, and means for preventing the voltage of said common battery included in said first office from being applied to any of said subscribers' lines.
32. In a telephone system, a first office, a second office, a trunk line connecting said offices, each of said offices including a common battery individual thereto for operating the apparatus therein, said batteries having their voltages so proportioned, and being so related to said trunk line, that the battery of said second office is charged from the battery of said first office, a plurality of subscribers' lines extending to said first office, each of said subscribers' lines having connected thereto at least one subscriber's substation of the local battery type and being accessible to a link line included in said trunk line, and means comprising condensers individually included in series with the individual conductors of said link line and the individual associated conductors of said trunk line for preventing the voltage of said common battery included in said first office from being applied to said subscribers' lines.
33. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said second-named group and each operative in response to its energization to connect the associated line to said suboffice trunk line, each of said line relays having an operating circuit energized in response to the initiation of a call on the associated line, and means responsive to the initiation of a call on any one of said first-named group of lines for interrupting the operating circuits for all of said line relays.
34. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said second-named group and each operative in response to its energization to connect the associated line to said suboffice trunk line, each of said line relays having an operating circuit energized in response to the initiation of a call on the associated line, and means responsive to the connection of any one of said first-named group of lines to said central office trunk line for interrupting the operating circuits for all of said line relays.
35. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said first-named group and each operative in response to its energization to connect the associated line to said central office trunk line, each of said line relays having an operating circuit energized in response to the initiation of a call on the associated line, and means responsive to the initiation of a call on any one of said second-named group of lines for interrupting the operating circuits for all of said line relays.
36. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said first-named group and each operative in response to its energization to connect the associated line to said central office trunk line, each of said line relays having an operating circuit energized in response to the initiation of a call on the associated line, and means responsive to the connection of any one of said second-named group of lines to said suboffice trunk line for interrupting the operating circuits for all of said line relays.
37. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said second-named group and each operative in response to its energization to connect the associated line to said suboffice trunk line, each of said line relays having an operating circuit energized in response to the initiation of a call on the associated line, an operator's telephone accessible to said central office trunk line, and means responsive to the connection of said operator's telephone to said central office trunk line for interrupting the operating circuits for all of said line relays.
38. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said first-named group and each operative in response to its energization to connect the associated line to said central office trunk line, each of said line relays having an operating circuit energized in response to the initiation of a call on the associated line, an operator's telephone accessible to said central office trunk line, and means responsive to the initiation of a call on any one of said first-named group of lines for interrupting the operating circuits for all of said line relays.

sive to the connection of said operator's telephone to said central office trunk line for interrupting the operating circuits for all of said line relays.

5 39. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said first and second-named groups, each 10 of the line relays associated with a line of said 15

first-named group being operative in response to its energization to connect the associated line to said central office trunk line, each of the line relays associated with a line of said second-named group being operative in response to its 5 energization to connect the associated line to said suboffice trunk line, each of said line relays having an operating circuit energized in response to the initiation of a call on the associated line, an operator's telephone accessible to said central 10 office trunk line, and means responsive to the connection of said operator's telephone to said central office trunk line for interrupting the operating circuits for all of said line relays.

EDWARD S. PETERSON. 15

CERTIFICATE OF CORRECTION.

Patent No. 2,145,127.

January 24, 1939.

EDWARD S. PETERSON.

It is hereby certified that error appears in the printed specification of the above numbered patent requiring correction as follows: Page 17, second column, lines 30 to 36 inclusive, claim 2, strike out the words and comma "means responsive to the operation of any one of said last-named means for rendering the other similar means inoperative to connect their respective associated lines to said central office trunk line in response to calls initiated on said respective associated lines," and insert the same before "impulsing" in line 28, same claim; and that the said Letters Patent should be read with this correction therein that the same may conform to the record of the case in the Patent Office.

Signed and sealed this 21st day of March, A. D. 1939.

Henry Van Arsdale.

Acting Commissioner of Patents.

sive to the connection of said operator's telephone to said central office trunk line for interrupting the operating circuits for all of said line relays.

5 39. In a telephone system, a central office, a suboffice, a tandem office, a central office trunk line connecting said central office and said tandem office, a group of lines accessible to said central office trunk line, a suboffice trunk line connecting said tandem office and said suboffice and accessible to said central office trunk line, a group of lines accessible to said suboffice trunk line, line relays individually associated with the lines of said first and second-named groups, each 10 of the line relays associated with a line of said 15

first-named group being operative in response to its energization to connect the associated line to said central office trunk line, each of the line relays associated with a line of said second-named group being operative in response to its 5 energization to connect the associated line to said suboffice trunk line, each of said line relays having an operating circuit energized in response to the initiation of a call on the associated line, an operator's telephone accessible to said central 10 office trunk line, and means responsive to the connection of said operator's telephone to said central office trunk line for interrupting the operating circuits for all of said line relays.
